UNITED STATES PATENT OFFICE.

EDWARD E. CLEMENT, OF WASHINGTON, DISTRICT OF COLUMBIA, ASSIGNOR, BY
MESNE ASSIGNMENTS, TO THE NORTH ELECTRIC MANUFACTURING COMPANY.

TELEPHONE-EXCHANGE SYSTEM.

Application filed July 15, 1907. Serial No. 383,875.

To all whom it may concern:

- Be it known that I, EDWARD E. CLEMENT, a citizen of the United States, residing at Washington, in the District of Columbia, 5 have invented certain new and useful Improvements in Telephone-Exchange Systems, of which the following is a specification, reference being had therein to the accompanying drawing.
- 10 My invention relates to telephone exchange systems, and particularly to so-called semi-automatic or semi-manual systems in which automatic switches are employed for connecting subscribers' lines, but, instead of controlling the automatic switches from the subscribers' stations as in the full automatic systems they are controlled by means of operators to whom the subscribers communicate the numbers of wanted subscribers.
- 15 The object of the invention is to simplify, and improve systems of this class in various particulars which will be hereinafter pointed out.
- In carrying out my invention I may locate the operators' equipments either in the 20 exchange or at a point removed from the exchange at which the connection of the subscribers' lines through switch trunks is effected, and may connect these operators' equipments with the exchange by means of operators' trunks. An operator's trunk may be defined as a conductor or conductors over which the operator is communicated with and over which the automatic selective 25 switches are controlled by the operator, as contradistinguished from a switch trunk over which conversation between subscribers is ordinarily carried on. It will appear hereinafter that I may also use the operators' trunks for directly connecting subscribers, but such is not the principal end of this 30 invention, being shown and claimed in my prior applications, Nos. 255,830 and 252,305, filed April 15, 1905 and March 27, 1905.
- 35 By thus providing means whereby the operators' equipments may be located at a distance from the exchanges which they serve, I am enabled to group the operators' equipments serving a plurality of exchanges, at a single point or office. With this arrangement operators' equipments may have apparatus in common whereby the cost of apparatus, construction, and maintenance is reduced. This arrangement also permits the 40 balancing of heavy traffic at a very busy ex-

change against light traffic at a less busy exchange so that the office at which the operators' equipments are located becomes a sort of traffic clearing house for the whole system and the number of operators' equipments and operators required are those which will be sufficient only to handle the maximum number of simultaneous calls in the whole system instead of the sum of the operators' equipments and operators at the 60 various exchanges, the number at each exchange being that required to handle the maximum number of simultaneous calls at that exchange.

Inasmuch as an operator's equipment and 70 the operator's trunk through which it operates is in use but a very short time for effecting each interconnection of two subscribers, I provide suitable connecting means whereby these trunks over which the operators control the subscribers' connections, may be made much less in number than the number of talking or switch trunks at the exchanges which are served. This enables a clearing house as described to be established 80 with a minimum amount of wiring.

In some cases the operator's control of connecting devices is effected through the talking trunks as well as the operators' trunks proper but by whatever means the operator 85 exercises control over the automatic switches, I believe that I am the first to group operators' equipments at a distance from an exchange or exchanges and provide trunks extending from said group to the exchange 90 or exchanges, the said trunks extending to an exchange being less in number than the number of talking trunks served at that exchange.

In the drawings forming a part of this application I have illustrated, and shall herein describe what I consider the best embodiment of my invention at the present time, but it will be understood that all of the illustration and description herewith and herein 100 are to be taken as typical and used for purposes of definition but not for limitation to specific forms.

In the accompanying drawings which illustrate the invention,—

Fig. 1 is a diagram showing the general arrangement of subscribers' stations, exchanges, operators' equipments and connections, according to the present invention, in which the operators' equipments are located 110

in an exchange to which subscribers' lines are connected.

Fig. 2 is a diagram showing another general arrangement in which the operators' equipments are not located at an exchange but at a point separated from all the exchanges, to which subscribers' lines are connected.

Fig. 3 is a diagram showing another general arrangement of apparatus as will be hereinafter referred to.

Fig. 4 is a general view of another arrangement which will be again referred to.

Fig. 5 is an end view and Fig. 6 is a side elevation of an impulse sending machine forming a portion of the operator's equipment.

Fig. 7 is a diagram showing subscribers' instruments and their connecting lines.

Fig. 8 is a diagram showing subscribers' cut-off and line relays and relays for selecting an idle trunk.

Fig. 9 is a diagram showing primary selector relays whereby connection with a trunk is established.

Fig. 10 is a diagram showing the primary selector relays of another trunk.

Fig. 11 is a diagram showing the primary selector relays of another trunk.

Fig. 12 is a diagram showing the calling end of a talking trunk.

Fig. 13 is a diagram showing an intermediate portion of a talking trunk with automatic selector switches for establishing connections for the same;

Fig. 14 is a diagram showing the called end of a talking trunk with an automatic connector switch for connecting the same;

Fig. 15 is a diagram showing apparatus for effecting selective ringing on party lines;

Fig. 16 is a diagram showing a secondary selector by which connection of a trunk with an idle operator's equipment is effected;

Fig. 17 and Fig. 18 are diagrams showing intermediate connecting devices including a plug and jack for connecting the secondary selector with the operator's equipment.

Fig. 19 is a diagram showing the connection of the sending machine; and an operator's key-set.

Fig. 20 is a diagram showing a modified means for connecting the secondary selector and the operator's equipment.

Fig. 21 is a diagram showing the connection of a sending machine and an operator's key-set adapted to be used in conjunction with the connecting device shown in Fig. 20 and

Fig. 22 is a diagram showing the manner in which Figs. 7 to 21 are to be arranged in order to set forth their relations to each other.

Referring to the drawings, there is shown therein apparatus of sufficient extent to illustrate a system constructed and ar-

ranged according to the present invention. This apparatus comprises a plurality of subscribers' stations A, B and C, the lines of which are equipped with cut-off relays M^a, M^b and M^c respectively and also with line relays N^a, N^b and N^c respectively. There are also trunk transfer relays, one per talking trunk, for controlling the circuits of the relays of the primary selectors while a trunk

70

distributing switch, PDS operates to energize a trunk transfer relay of an idle talking trunk upon the call of a subscriber. The primary selectors, of which one is shown in each of the Figs. 9, 10, and 11, are for the purpose of connecting the line of a calling subscriber with their respective talking trunks. Each primary selector comprises a

75

plurality of tens relays each of which is adapted to partially effect the connections for a plurality of subscribers' lines and unit relays, each of which is adapted to complete the connection for a subscriber's line, thus partially connected, with a talking trunk. In Fig. 11 the tens relays are designated by PTR, PTR' and PTR² and the units relays

80

by PUR to PUR⁴ inclusive, in Fig. 9 the tens relays are indicated by PTR³, PTR⁴ and PTR⁵ and the units relays by PUR⁵ to PUR⁹ inclusive, and in Fig. 10 the tens relays are denoted by PTR⁶, PTR⁷ and PTR⁸ and the units relays by PUR¹⁰ to PUR¹⁴ inclusive. To each of the primary selectors is connected a talking trunk the calling end of one of which is shown in Fig. 12. From the calling end, the talking trunk extends

85

through automatic selector switches as shown in Figs. 13 and 14 and terminates in an automatic connector switch shown at the right hand end of Fig. 14.

90

The primary selectors illustrated and described in this case may be and preferably are grouped as to proper relays in decimal relation, that is to say, with ten tens relays and ten units relays to each trunk, accommodating one hundred lines, which are multiplied into each of ten groups of relays. In other words, the most convenient arrangement in practice is to divide the lines into groups of one hundred, allot ten trunks per one hundred lines, and then multiply the lines each ten times. This arrangement is not invariable, and the lines may be multiplied into different groups.

95

It will be understood that when the lines are grouped in the decimal manner above referred to, the distributing switches are also assigned preferably to particular groups. This will sufficiently appear from the detailed description.

100

The selector and connector switches (see Figs. 13 and 14) are of the well known Strowger type which are worked by current impulses in a well known manner. To supply the impulses for working the selector and connector switches operators' equipments are

110

115

120

125

130

associated with the trunks and each of these also comprises a telephone set of usual construction whereby the operator is placed in conversational communication with the calling subscriber and may ascertain from him the number of the wanted subscriber and send the impulses accordingly. The apparatus by which an idle operator's equipment is connected is similar to the means by which 5 an idle talking trunk is selected and connected with a calling subscriber. It comprises a plurality of transfer relays SDR (see Fig. 16) of which an idle one is automatically selected by means of a secondary 10 distributing switch SDS, the operating magnet of which is multiplied into a plurality of the trunks, while in each secondary transfer relay each trunk is represented by two pairs of contacts, the contacts corresponding to a 15 given trunk in the several relays being multiplied together. For connecting the trunk with the idle operator's equipment selected, a secondary selector is provided which is similar to the primary selector and comprises 20 tens relays STR, STR' and STR² and units relays SUR to SUR⁹ inclusive. Each talking trunk is represented in one tens relay of the secondary selector corresponding to each operator's equipment by two pairs of contacts, the contacts in the tens relay of one 25 secondary selector, which correspond to a given trunk being multiplied with the corresponding contacts in a tens relay of all the other secondary selectors so that any trunk 30 may be connected with any operator's equipment. An operator's equipment comprising her telephone and an impulse sending outfit together with apparatus and connections through the instrumentality of which, a secondary 35 selector, and a secondary transfer relay operate to establish connections of the equipment with a calling talking trunk, is shown in Figs. 17, 18 and 19.

Having thus given a general view of the 40 apparatus it will now be described in detail:

Taking for instance the subscriber's station A. which, with its line is typical of the others, it will be seen that from the station extend two conductors 1 and 2 which are 45 respectively connected with the armatures m^a and m'^a of the cut-off relay M^a. To the front contacts of these armatures are respectively connected the conductors 3 and 4 which form extensions of the subscriber's 50 line to the group of conductors MT of which more will be said hereafter. One terminal of the magnet of the relay M^a is connected to the conductor 4 so that the battery can be applied to the magnet over that conductor, the other terminal of the magnet being grounded as shown. The back contact of the armature m'^a is grounded while the back contact of the armature m^a is connected with one terminal of the magnet of the line 55 relay N^a, the other terminal of the line relay

magnet being connected with the wire 5 which is connected to the free terminal of battery B the other terminal of the battery being grounded. It will thus appear that the cut-off relay controls the line relay, the circuit 60 of the line relay being closed when the cut-off relay is deenergized and broken when the cut-off relay is energized. The line relay controls the magnet of the primary distributing switch PDS by means of its armature n^a and its front contact, the former being connected to the battery wire 5 and the latter to a wire 6 which is multiplied to the corresponding contacts of the line relays of a 65 plurality of subscribers' lines, so that battery 70 connection is thrown on it upon the energization of the line relay of any of a plurality of subscribers. This wire 6 is connected with one terminal of the magnet of the primary distributing switch PDS, the other terminal of that magnet being connected with ground through an interrupter I which is preferably continuously rotating. The armatures n^a and n'^a of the line relay 75 are connected with the battery wire 5 while each of these armatures has a front contact connected with one of the conductors of the group D. The group of conductors D extends to all the trunk transfer relays and 80 serves to respectively multiple together corresponding contacts upon one side of a plurality of trunk relays so that when battery connection is thrown upon two of these wires by the energization of a line relay, this connection will be extended to contacts in each 85 of the trunk transfer relays. It will now be seen that the energization of the line relay of a subscriber's line will result in the throwing of battery connection on to contacts in each of the trunk transfer relays. Upon the 90 energization of any one of the trunk transfer relays, these battery connections will be thrown on two particular conductors of a group E, E' or E'' which leads from the 95 energized trunk relay to a primary selector. 100 Thus, the energizing of the line relay N^a serves to connect the conductors 7 and 8 of the group D with battery and these conductors are respectively connected with the contacts 9 and 10, 9' and 10', and 9'' and 10'' of the trunk transfer relays TR, TR' and TR'' and so on to any other number of 105 trunk transfer relay. Upon the energization of any trunk transfer relay as for instance TR' the battery connection to the contacts 9' and 10' will be respectively thrown upon the conductors 11 and 12 of the group E' through which battery connection is afforded to relays of the primary selector shown in Fig. 9 as will be hereinafter referred to. The 110 trunk transfer relay which is energized in any given instance is that one, corresponding to an idle trunk, with which the primary distributing switch first establishes connections. 115 To refer in detail to the primary distributing 120 switch PDS, it will be seen that the contacts 125 130

switch, it will be seen that it comprises a series of contacts *c* to each of which is respectively connected one terminal of a trunk distributing relay. Over these contacts a movable member *a* is adapted to travel, the said member making successive contacts with the contacts *c*. This movable member of the switch is electrically connected with the wire 6 so that when battery is thrown upon this wire it is also thrown upon the movable member and therefore battery connections will be thrown in succession upon contacts *c* as the member comes into successive engagement with them. This operates to successively throw battery connection on the various trunk transfer relays. To effect the movement of the movable member over the contacts *c* a ratchet *r* is secured thereto, the said ratchet being adapted to cooperate with a pawl *p* which is connected with the armature of the magnet of the primary distributing switch and is reciprocated thereby. The reciprocation of the armature results in the turning of the movable member in the direction as indicated by the arrow and having once been initiated by the energization of any subscriber's line relay, the reciprocation will continue until the subscriber has been connected with a talking trunk when the line relay will become deenergized. The movable member might comprise but a single arm. In that case, however, unless the contact *c* extended over practically the entire circumference of a circle, considerable time would be lost while the arm, after having left the last contact *c* would be brought into engagement with the first one of the contacts *c*. In the present instance the contacts *c* have been shown as extending over an arc of approximately 120 degrees and to avoid the loss of time indicated, the movable member comprises three arms at angles of approximately 120 degrees from each other so that when one of the arms leaves the contact *c* another will be in position to enter upon them and the delay as noted will be avoided. It will be understood of course that the arc over which contacts *c* extend might be any other than 120 degrees and where such is the case the arms would correspond in both number and arrangement.

While, as a movable arm of the primary distributing switch passes over the contacts *c*, battery is successively thrown on a terminal of each of the trunk distributing relay magnets, the other terminal of each of those magnets is or is not connected with ground according to whether or not its corresponding talking trunk is idle. The ground connection of each of these magnets is controlled by a talking trunk relay which relay breaks the ground connection when the trunk is in use and closes it when the trunk is idle. It will now be apparent that after a call and as the movable member of the primary dis-

tributing switch moves over the contacts *c*, and battery is successively thrown on the trunk transfer relays, no effect will be produced as long as contacts corresponding to the trunk transfer relays of busy trunks are engaged, but so soon as a contact *c* connected with the relay of an idle talking trunk is reached, the circuit of the magnet of that relay will be completed and connections will be established with the primary selector of the talking trunk corresponding to the relay energized.

The primary selectors, comprise tens and units relays as before indicated. A group MT of conductors extends to a plurality of primary selectors and the conductors within this group serve to respectively multiple each subscriber's line contact upon one side of each tens relay with the corresponding contact of the corresponding tens relay of the other primary selectors. Thus, the conductor 13 connects the contact 14 of the tens relay PTR³ of the primary selector of Fig. 9 with the contact 15 of the tens relay PTR of the primary selector of Fig. 11 and also with the contact 16 of the relay PTR⁶ of the primary selector shown in Fig. 10. Similarly the contacts 17, 18 and 19 of the tens relay PTR³, PTR and PTR⁶ respectively are connected together by the conductor 20 of the group MT.

The subscribers' contacts of the tens relays on the other side from those referred to as being connected with the conductors MT, are each multiplied to the corresponding contacts of all the tens relays in the same primary selector by means of conductors in the groups MT^a, MT^b, and MT^c, respectively. Thus in the primary selector shown in Fig. 9, the contacts 21, 22 and 23 of the tens relays PTR⁵, PTR⁴ and PTR³, respectively, are multiplied together by the conductor 24 in the group MT^b.

There are as many units relays per primary selector as there are subscribers' lines controlled by each tens relay in the selector. Each units relay has two pairs of subscribers' contacts, enough to connect one subscriber's line.

The two subscribers' contacts upon one side of each units relay are respectively connected to two conductors of the group, which multiple together the tens relay contacts within the selector, and therefore they are connected to two contacts in each tens relay of the selector. Thus, in Fig. 9 the units relay PUR⁷ has the pair of subscribers' contacts 25, 26 and 27, 28, the contacts 25 and 27 being respectively connected through the wires 28 and 29 with the conductors 30 and 31 and therefore with the contacts 32 and 33 of the relay PTR⁵, contacts 34 and 35 of the relay PTR⁴ and contacts 36 and 37 of the relay PTR³. The subscribers' contacts upon the other sides of all the units relays of a

- primary selector are multiplied together and to the end of a talking trunk. Thus, the contact 26 of the relay PUR⁷ in Fig. 9, is multiplied with the corresponding contacts 5 in the other units relays of the selector by means of the conductor 38 which is connected with the conductor 39 of the talking trunk while the contact 28 of the relay PUR⁷ is multiplied with its corresponding contacts 10 in the other units relays of the selector by means of the conductor 40 which is connected with the conductor 41 of the talking trunk.

Reference has been made to subscribers' contacts of the tens and units relays. By this term is meant the contacts which connect the subscribers' lines with the trunks. In addition to the subscribers' contacts each tens relay is provided with a pair of contacts 20 for locking the circuit of its magnet after the circuit, by which the magnet was initially energized, has been broken. Thus the relay PTR⁴ is provided with a pair of contacts 42 and 43. Contact 42 upon one 25 side of the relay is connected with one terminal of its magnet, while the contact 43 upon the other side of the relay is multiplied by a conductor 44 with its corresponding contacts in the other tens relays of the selector. Similarly each units relay is provided with a pair of contacts for locking the 30 circuit of its magnet. Thus the relay PUR⁷ has contacts 45 and 46, the contact 45 on one side being connected with one terminal of the magnet of its relay, while the contact 46 is multiplied with its corresponding contacts 35 in the other units relays of the selector by means of a wire 47. The wires 44 and 47 are both connected with a wire 48 through 40 which is made a battery connection controlled by a relay of the talking trunk, as will be shown hereinafter. One terminal of each of the magnets of the tens and units relays is connected with ground as shown. 45 The other terminal of each of these relays is connected by a wire with a contact in the trunk distributing relay corresponding to the primary selector in which the tens or units relay is located, this in addition to the 50 connection of the magnet terminal with the locking contacts of its relays as before referred to. Thus the terminal of the magnet of the tens relay PTR⁸, which terminal is connected to the locking contact 49 of its 55 relay, is also connected by means of the conductor 12 in the group E' with the contact 50 of the trunk distributing relay TR'. Similarly the magnet of each units relay has one terminal connected with a locking 60 contact of its relay and is also connected with a contact in its corresponding distributing relay. Thus, the terminal of the magnet of the units relay PUR⁷ which is connected with the locking contact 45 of its relay is also connected by means of the con-

ductor 11 in the group E', with the contact 51 of the trunk distributing relay TR'. The contacts and connections are so arranged that when a trunk relay is closed, the battery connections herein before referred to as 70 thrown upon certain of the conductors in the group D by the operation of the line relay of a subscriber's line, will be thrown upon the two conductors connected to contacts on the other side of the trunk distributing relay, which conductors respectively lead to the tens relay and the units relay of the primary selector corresponding to the closed trunk distributing relay, which 75 tens and units relays are assigned to the particular subscriber calling. Thus, when the subscriber A calls and his line relay N^a is energized, battery connection is thrown upon all the contacts connected with the conductors 7 and 8 in the group D as before referred to. It being assumed that the trunk distributing relay TR' corresponds to the first idle trunk and therefore that this relay is energized by reason of the call of the subscriber at the station A, the contacts 9' and 80 10', being two of the contacts which are respectively connected with battery, will be respectively brought into engagement with the contacts 51 and 50 whereby battery will be thrown upon the conductors 11 and 12 85 and therefore upon one terminal of each of the relays PTR⁸ and PUR⁷, whereupon these relays will become energized and the contacts upon the opposite sides of the respective relays will be brought together, the tens 90 relay connecting respectively a plurality of pairs of conductors in the group MT with pairs of conductors in the group MT^b of the particular selector to which the tens relay belongs, thus partially establishing the connection of all the conductors in the group 95 MT, which are connected with the particular tens relay, with the talking trunk corresponding to the selector. Of these conductors MT^b thus connected with the conductors 100 of the group MT that pair connected with the contacts of the units relay PUR⁷ will be connected with the conductors of the talking trunk, the units relay serving to complete the connection with the trunk of one 105 of the pairs of conductors in the group MT, a plurality of pairs of which conductors were partially connected by the tens relay. It will now appear that a call by a subscriber 110 operates to throw battery connection upon a plurality of conductors, which conductors are connected through the contacts of a trunk distributing relay with the magnets respectively of a tens and a units relay in the primary selector corresponding to the trunk distributing relay energized, which tens and units relays are those to which the particular calling subscriber has been assigned, the tens relay closing the contacts for a plurality of subscribers' lines, among which is 115 120 125 130

the calling subscriber's line, while the units relay completes the connection with the talking trunk of the particular contacts of the tens relay which correspond to the calling subscriber's line.

To briefly recapitulate, each talking trunk is provided with a primary selector which consists of tens and units relays. The subscribers are divided into groups, each group being represented by a tens relay in each of the primary selectors, the subscribers' lines connected to the plurality of contacts controlled by the tens relay in one primary selector being multiplied to the corresponding contacts of the corresponding tens relay in all the other primary selectors, so that any particular group of subscribers may be connected in any primary selector by energizing the tens relay corresponding to that group in any primary selector. There will obviously be as many tens relays per primary selector as the number of groups into which the subscribers are divided and each tens relay will have a sufficient number of contacts to connect the number of subscribers' lines which have been assigned to it. Those contacts of the tens relays on the opposite sides from those just referred to as multiplied between the primary selectors are multiplied together within the primary selectors and each set of these multiplied contacts is connected with the contacts upon one side of a units relay, the number of units relays corresponding to the number of sets of multiplied contacts, or in other words, to the number of subscribers controlled by each tens relay. The contacts upon the other side of the units relays are multiplied, as before described, to the talking trunk to which they correspond, the closing of the contacts of any particular units relay thus operating to connect two of the multiplied sets of contacts in the tens relays with the trunk. While a given group of subscribers' lines is adapted, as just described, to be connected by the operation of a tens relay in any primary selector, the primary selector in which the contact is actually formed is determined by the trunk distributing relays, of which there is one corresponding to each talking trunk and its primary selector. A trunk distributing relay corresponding to an idle talking trunk is selected and energized, as before described, and this operates to throw battery connections on the magnet of a tens and a units relay of the particular primary selector to which the trunk distributing relay corresponds, the arrangement and connections being such that the particular tens relay and the particular units relay which are thus energized correspond to the group to which the particular calling subscriber is assigned and to the particular subscriber, respectively.

In practice, it is preferred to arrange the

primary selector according to the decimal system. According to this system contacts would be assigned to each tens relay sufficient to serve ten subscribers' lines, and there would be ten units relays per trunk, the number of tens relays per trunk being equal to that number by which ten must be multiplied to equal the total number of subscribers served. It will be understood, however, that other arrangements might be employed. In a concrete illustration it is necessary to show a particular number of contacts, relays, and other apparatus and therefore it will be understood from the description herein that the contacts, relays, and apparatus shown herein are for purposes of illustration and that they might be increased or diminished in number or changed in arrangement, as will be obvious after a perusal of the description. In various places complete connections of apparatus shown are omitted, as these connections would readily be supplied by persons skilled in the art, they being merely extensions or duplicates of precisely similar apparatus and connections which are described in detail.

Referring now particularly to Fig. 12, there is therein illustrated the calling end of a talking trunk. It will be understood that there is one of these trunks corresponding to each primary selector, the number of trunks and primary selectors being dictated by the amount of traffic to be handled, but inasmuch as these trunks are precisely alike, one will serve to illustrate each, and for purposes of illustration the trunk shown in Fig. 12 will be assumed to correspond to the primary selector shown in Fig. 9.

The talking trunk conductors 39 and 41 are respectively connected with the conductors 38 and 40, to which are multiplied the contacts of the units relays of the primary selector, as before described. To the conductors 39 and 41 are respectively connected the tip and sleeve relays R and R', the magnet of the tip relay R being connected at one side with ground and at the other with the conductor 39, while the sleeve relay R' is connected upon the one hand with the conductor 41 and upon the other to the battery wire 52, which is connected with the free terminal of the battery B', the other terminal of the battery being connected with ground, as shown. It will now appear that when a subscriber's line is connected with the trunk, the receiver in that case being removed from its hook, the tip and sleeve relays will be bridged between the free terminal of the battery and ground and will therefore be energized.

The tip relay R, by means of its armatures 1^r and 2^r, controls the clearing out of the automatic apparatus and by means of its armature r controls the connection of the wire 48 with battery, this wire being that

through which the battery connections of the magnets of the tens and units relays are made, as hereinbefore referred to. The sleeve relay R' , by means of its armatures 5 1' and 2', initially controls the battery connections of the wires 53 and 54 which lead through the secondary distributing relay SDR to the tens and units relays, of a secondary selector, corresponding to the particular trunk, these conductors 53 and 54 being multiplied onto the corresponding contacts of a plurality of secondary distributing relays by means of conductors 55 and 56, so that the battery connection established by this trunk may be thrown upon the magnets of the secondary selectors of any operator's equipment by the operation of the secondary distributing relay corresponding to that secondary selector. The 10 battery connection through the conductors 53 and 54, after having been completed by the attraction of the armatures 1' and 2', when a calling subscriber's line is connected to a trunk, is broken at the armatures 75 1' and 1² of the relay R^3 which becomes energized when a secondary selector has operated to connect an operator's equipment. The sleeve relay R' by means of its armature 1' also initially controls the battery connection 20 of the wire 57 which is connected with the magnet and movable member of the secondary distributing switch SDS, this connection being established when the relay R' is energized, and broken at the armature 2² when 25 the relay R^3 is energized. The ground connection of the relay R^3 is made through the magnet of the relay R^2 so that the magnets of these two relays are connected in series and are simultaneously energized and de- 30 energized. The relay R^2 by means of its armature 1² establishes, when deenergized, the battery connection of the wire 48. When the wanted subscriber has been connected and the relay R^2 energized the battery connection 35 of the wire 48 through the armature 1² will be broken, this connection being maintained by the armature 1, the control of the battery connection of the primary selector magnets being then controlled by 40 the relay R . During the energization of the relay R^2 , that is during the connection of subscribers' stations, battery connection will be thrown upon the armatures 1' and 2', so 45 that upon the de-energization of the relay R , which occurs upon the hanging up of the receiver at the close of the conversation, the armatures 1' and 2' will throw battery simultaneously upon the talking trunk wires thereby restoring the automatic switches, as 50 will hereinafter appear. The wire 57 is multiplied by means of a wire 58 with the corresponding wires of the other trunks, so that the secondary distributing switch SDS 55 may be set in operation by the calling of any of the trunks.

The conductors 39 and 41 of the talking trunks are respectively extended by conductors 59 and 60, the connection between the conductors 39 and 41 on the one hand and conductors 59 and 60 on the other being effected by means of condensers K and K', the connections thus formed being inductive which permits the transmission of variable voice currents while preventing the transmission of steady or battery currents, so that the desired connection between subscribers' lines is secured without confusing the battery currents flowing in the conductors. The talking trunk is extended forward from the conductors 59 and 60 to the first selector 70 switch S' by means of the conductors 61 and 62, the connections between the conductors 59 and 60 on the one hand and 61 and 62 on the other being effected by the armatures 1⁴ and 1⁵ of the relays R^4 and R^5 . The relays R^4 and R^5 are combined cut-off and repeating relays, the relay R^4 operating to cut off the conductor 61 from the conductor 59 and transmit so-called vertical impulses over the former wire to actuate the Strowger switches, while the relay R^5 operates to disconnect the conductor 60 from the conductor 62 and transmit so-called rotary impulses over the latter conductor to the Strowger switches. One terminal of the magnet of the relay R^4 is connected to ground, as shown, the other terminal of that magnet being connected with a wire 63; while one terminal of the magnet of the relay R^5 is connected with the free terminal 75 of the battery B', the other terminal of that magnet being connected to the wire 64. The wires 63 and 64 are connected to contacts in one of the tens relays STR² of a secondary selector, and are multiplied by means of conductors 65 and 66 with the corresponding contacts in the corresponding tens relay of a plurality of other secondary selectors so that the relays R^4 and R^5 of the talking 80 trunk can be connected to any operator's equipment. When the lines 63 and 64 have become connected through to an operator's equipment and the listening key has been depressed, the operator's telephone set is bridged across the lines 63 and 64, and thus 85 a bridge between the free terminal of battery and ground is formed through the magnets of the relays R^4 and R^5 and through the operator's telephone set. The magnets of 90 these relays, therefore, attract their armatures, and the talking trunk conductors 59 and 60 on the one hand are broken apart from the conductors 61 and 62 on the other. The armatures 1⁶ and 1⁷ of the relays R^6 and R^7 respectively, being attracted, circuit is made from the free terminal of the battery B' through the armatures just referred to and the magnet of the relay R^6 to ground. The energization of the relay R^6 95 results in the attraction of its armatures 100

⁷⁶ and 1⁶, these armatures being respectively connected to the talking trunk conductors 59 and 60. The front contacts of these armatures are respectively connected by means of wires 67 and 68 with the wires 63 and 64 leading to the operator's equipment. It will therefore appear that when the operator's telephone set is bridged across the conductors 63 and 64 not only are the conductors 59, 60, 61 and 62 broken apart, as mentioned, but the operator's telephone set is bridged across the conductors 59 and 60 so that conversation may be carried on with the calling subscriber. In order to avoid such diversion of the talking currents as to interfere with conversation the magnet coils of the relays R⁵ and R⁴ are made of such ohmic resistance that they do not unduly oppose the passage of steady currents but oppose a very high reactance to the passage of the varying talking currents. This provision is to be observed in all cases where there is a bridge across the talking conductors, as for instance in the case of the relays R and R'. The battery B' supplies the talking current for the operator's telephone.

When the relays R⁴ and R⁵ are simultaneously energized, as described, the armature 2⁴ of the relay R⁴ breaks the battery connection which otherwise would be thrown on the armature r⁵ and therefore on the sleeve conductor 62 of the talking trunk. In a similar manner the armature 2⁵ of the relay R⁵ breaks the battery connection which would otherwise be thrown upon the armature r⁴ and therefore upon the tip conductor 61. The attraction of the armature 2⁵ of the relay R⁵ operates to throw battery upon one terminal of the magnet of the relay R³ and therefore the relays R² and R³ become energized. This results in the breaking of the battery connection of the wire 48 from the armature r², but this connection is now maintained through the armature r. It also results in the breaking of the battery connection of the wires 53 and 54 at the armatures r³ and 1³ thereby breaking the initial battery connections of the tens relay and the units relay in the secondary selector which correspond to the trunk connected. These tens and units relays are now, however, locked closed and the breaking of the connections through the wires 53 and 54 has no effect upon them. A further result of the energization of the relay R³ is the attraction of the armature 2³ whereupon the battery connection of the wire 57 is broken, thus cutting off the supply of current to the magnet of the secondary distributing switch, whereupon that switch stops. The attraction of the armature r² of the relay R² in addition to breaking the battery connection of the wire 48 throws battery upon the armatures 1² and 2² but, at this time, these armatures being attracted, they are not in engagement with their contacts. The armature 2³ when attracted, in addition to breaking the battery connection of the wire 57, locks battery upon the magnet of the relay R³ through the armature r'. The attraction of the armature 3^r of the relay R' results in the breaking of the ground connection of the wire 70 thereby removing that connection from the trunk distributing relay TR' which corresponds to the trunk thereby affording a busy test as hereinbefore referred to, it not being possible for the switch PDS to establish a circuit through the trunk distributing relay referred to even though one of the switch arms may rest upon the contact to which the relay is connected.

Referring now to the secondary selector shown in Fig. 16 and which is an example of all the secondary selectors, it will be noted that this selector is very similar to the primary selector of a talking trunk as hereinbefore described, the relations which the secondary selectors bear on the one hand to a calling trunk, that is one to which a calling subscriber has been connected, and on the other hand to the operator's equipment, being precisely similar to the relations which a primary selector bears to a calling subscriber on the one hand and the talking trunks on the other; thus a plurality of talking trunks each have wires, as 53 and 54, assigned to particular contacts in each of the secondary distributing relays, as SDR, the conductors as 53 and 54 of each trunk being multiplied to the corresponding contacts in a plurality of these secondary distributing relays. These relays, as SDR, correspond with the trunk distributing relays associated with the primary selectors. It will now be seen that upon the operation of any secondary distributing relay, as SDR, the conductors from a trunk, as 53 and 54, will be connected with the secondary selector corresponding to that distributing relay. The selection of the secondary distributing relay to be energized upon the calling of a trunk is effected by means of a secondary distributing switch SDS which is similar in all respects to the primary distributing switch PDS hereinbefore referred to. When a trunk calls, the movable member of the secondary distributing switch is stepped about over the stationary contacts until a contact connected with a distributing relay corresponding to an idle operator's set is reached. The effecting of a connection with an operator's equipment operates to stop the switch in a manner analogous to that in which the primary distributing switch is stopped upon the connection of a talking trunk with the calling subscriber. The ground connection of each of the secondary distributing relays is controlled by a relay associated with the operator's equipment.

ment, the ground connection being removed from a secondary distributing relay when its corresponding operator's equipment is in use or busy, so that no succeeding calling 5 trunk can cause energization of the secondary distributing relay of a busy operator's equipment.

The tens and units relays, herein referred to, of each secondary selector are arranged 10 similarly to the tens and units relays of a primary selector, thus we have the contacts upon one side of each of the tens relays connected with a plurality of wires, as 63 and 64, coming from a plurality of trunks, 15 each trunk being multiplied into the corresponding contacts of the corresponding tens relays of all the other secondary selectors, so that any trunk may be connected through any secondary selector with an operator's 20 equipment. Those contacts upon the other sides of the tens relays from those in which the contacts connected to wires, as 63 and 64, are located, are respectively multiplied together within the secondary selector, a 25 given contact in one tens relay being multiplied with the corresponding contact in each of the other tens relays of the selector. Obviously there are provided in each secondary selector a number of tens relays 30 which shall equal the number of trunks served divided by the number served by one relay. The units relays correspond in number to the number of trunks served by one tens relay and each comprises contacts which 35 upon the one hand are connected with those contacts of the tens relays which are multiplied within the selector, and on the other hand are multiplied to wires, as 71 and 72, extending to the operator's equipment. It 40 will be obvious that since the contacts upon one side of a units relay, which are multiplied together throughout the selector with corresponding contacts in all of the units relays of the selector will be connected with 45 the wires 71 and 72 by the energization of a units relay. To restate the matter, the closing of a tens relay operates to partially close the connections of conductors, as 63 and 64, of a plurality of trunks and the connection 50 of the conductors corresponding to anyone of the trunks may be completed to the conductors 71 and 72 by closing a units relay. It is therefore necessary in order to establish the connection of a calling trunk with 55 an operator's equipment to close the tens relay controlling the group of connections to which the particular trunk has been assigned and also to close the units relay corresponding to the particular contacts in the 60 closed tens relay to which the trunk is assigned. To energize a tens and a units relay for effecting the connections as indicated, the circuit is completed from battery at the calling trunk through wires, as 53 and 54 of the 65 secondary selector which is selected by the

secondary distributing switch SDS to the magnets of the particular tens relay and the particular units relay to which the trunk has been assigned. Each of the magnets of the tens relays and also those of the units 70 relays are upon one side connected with ground so that the forming of the battery connections, as described, results in their energization and the closing of the contacts which they control. It will be observed, 75 of course, that the contacts of the secondary distributing relay and the conductors connected thereto are so arranged that when the distributing relay is closed battery will be thrown on the tens and units relays which 80 correspond to the particular trunk seeking connection. In addition to the contacts referred to in the tens and units relays for connecting the talking trunk with the operator's equipment each relay, both tens and 85 units, has its battery terminal connected with one of its contacts. The contact in each tens relay opposite that contact to which the magnet terminal is connected is multiplied with the corresponding contacts 90 in all of the tens relays by a wire 72', and similarly a contact in each of the units relays which is opposite the one connected with its magnet is multiplied with the corresponding contacts in all the other relays 95 by a wire 73. The wires 72 and 73 are connected together and to battery, the ground connections of these relays being controlled by the operator's equipment. When, therefore, a tens and a units relay have been attracted, a battery connection is locked upon the magnets of those relays independent of the secondary distributing relay, so that the distributing relay may be deenergized without affecting the energized tens and units 100 relays.

But a single secondary selector has been shown but the relation which this selector will in practice bear to a plurality of talking trunks and to other secondary selectors 110 has been fully explained so that anyone skilled in the art would have no difficulty whatever in adding trunks and secondary selectors as required.

The wire 74 for establishing ground connection of the magnets of the tens and units relays, the wire 75 establishing the ground connection for the secondary distributing relay, and the wires 71 and 72 through which the operator's equipment is connected 115 with the trunk, extend from the secondary selector, shown in Fig. 16, to the apparatus shown in Fig. 17, the latter figure showing intermediate apparatus for connecting the operator's equipment with the secondary selector and thence with the trunk, the apparatus shown in Fig. 17 being used in conjunction with that shown in Fig. 18 and comprising a plug and jack connection. The apparatus shown in Fig. 17 comprises 120 125 130

the three relays R^7 , R^8 and R^9 , a signal lamp L for notifying the operator of a call, and a jack J . Upon the connection with the trunk of the apparatus shown in Fig. 17, this connection being established through the tens and units relays of the secondary selector and conductors as 63 and 64, the relay R^8 of the apparatus shown in Fig. 17 is connected through the wires 72 and 64 with the relay R^5 of Fig. 12. One terminal of the relay R^8 being connected with ground as shown and a terminal of the relay R^5 being connected with battery as before described, the two relays will be connected in series between the battery and ground whereby the relay R^8 will be energized. The energization of the relay R^8 results in the throwing of a battery connection on the relay R^7 by means of the armature r^8 , the other terminal of the relay R^7 being grounded as shown. The relay R^7 being thus energized attracts its armatures whereupon the ground connection of the wire 75 is broken at the armature 1^7 thus placing a busy test upon the secondary distributing relay STR as before indicated. The initial ground connection for the wire 74 of the secondary tens and units relays which was established through the armature 2^7 , is also broken upon the energization of the relay R^7 but this ground connection is maintained by the armature 1^8 which, as will be observed was attracted prior to the energization of the relay R^7 . The energization of relay R^8 and the attraction of its armature 2^8 places battery connection upon one terminal of the signal lamp L the other terminal of that lamp being connected with ground. The attraction of the armature r^7 of the relay R^7 results in the connection of one terminal of the magnet of that relay with a front contact of one of the armatures of the relay R^9 and through this connection battery is locked upon the magnet of the relay R^7 when the relay R^9 is energized which occurs later. One terminal of the relay R^9 extends to a jack contact j^a through which a ground connection of the relay R^9 is made when the operator inserts her plug. When the plug is inserted and the relay R^9 is energized, the circuit of the magnet of the relay R^8 will be broken at the armature r^9 whereupon the relay R^8 will become deenergized and release its armatures. This results in the breaking of the battery connection of the relay R^7 at the armature r^8 but this connection is now locked on that relay by the armature 1^9 . Also a ground connection of the wire 74 will be broken at the armature 1^8 but this connection will be maintained by the armature 2^9 , while the release of the armature 2^8 results in the extinguishment of the signal lamp L . It will now appear that the relay R^9 controls the tens and units magnets of the secondary selector and also the busy test upon the sec-

ondary distributing relay and that this relay R^9 is controlled by the plug in the jack J . In addition to the contact j^a the jack J also has contacts j^b and j^c which are respectively connected with the wires 72 and 71 through 70 which conversation is carried on by the operator and over which signals for the operation of the automatic selector and connector switches are sent.

Referring now to Fig. 18, in which is shown a plug P adapted to cooperate with the jack J of Fig. 17, it will be seen that the contact p^e is adapted to engage with the spring contact j^e , contact p^b is adapted to engage with the spring contact j^b and a contact p^a is adapted to engage with the sleeve contact j^a . It will now appear that when the plug is inserted the conductor 76 will form an extension of conductor 71, the conductor 77 connected with the contact p^b will form 85 an extension of the conductor 72 while the conductor 78 connected to the contact p^a will form a continuation of the conductor connected with the contact j^a of the jack which is connected to one terminal of the magnet 90 of the relay R^9 .

The relay R^{10} controls the connection of the operator's telephone across the wires 77 and 76. One terminal of the magnet of this relay is connected with the free end of the battery B^2 while the other terminal of the magnet has its connection with ground controlled through the wire 79 by the operator's listening key. The armatures of the relay, r^{10} and 1^{10} are respectively connected with 100 the conductors 77 and 76 and, upon attraction, are adapted to engage with the wires 80 and 81 respectively to which the operator's telephone is connected. The operator's telephone may be of usual construction and is therefore not illustrated.

The wires 76 and 77 are conducted on beyond the points at which the connection of the operator's telephone is made, and by means of the relays R^{11} , R^{12} and conductors 110 82 and 83 to the sending machine shown in Fig. 19, by which impulses are transmitted to the trunk and forward to the automatic selector and connector switches. The relays R^{11} and R^{12} operate to control the connections of the sending machine with the trunk as will hereinafter appear. The relays last referred to are controlled by the operator's starting key S^k which when closed, operates to connect the wire 84 with ground. This wire 84 is connected with one terminal of the relay R^{12} while the other terminal of that relay is connected with the conductor 85 which is connected with the free terminal of the battery B^2 . The energizing of the relay R^{12} by the closing of the starting key results 115 in the throwing of a ground connection upon the magnet of the relay R^{11} through the armature 3^{12} , the other terminal of that relay being connected to the battery wire 85. The 120 125 130

energizing of the relays R^{11} and R^{12} operates to lock ground connections on them respectively through the wires 86 and 87 and through the armatures 2^{r11} and 2^{r12} under 5 conditions as will hereinafter be referred to. The armature 3^{r11} of the relay R^{11} when unattracted, forms through its back contact a ground connection for the wire 78 which has already been referred to as being connected 10 through the contact j^a of the jack J, with one terminal of the relay R^9 . It will thus be seen that the circuit of the magnet of the relay R^9 is completed upon the insertion of the plug P in the jack J. The attraction 15 of the armature 3^{r11} breaks this ground connection and throws ground upon its forward contact which through the wire 88 and the signal lamp SL is connected with the free terminal of the battery B^3 . 20 It will now appear that this signal lamp will be energized during the energization of the relay R^{11} . The wires 86 and 87, already referred to as those through which ground is locked upon the relays R^{11} and R^{12} , and it is 25 also to be observed that the conductor 78 is connected with the wire 87, are grounded through pairs of contacts 89 and 90 respectively. These contacts are normally closed but are controlled by means of a revolving 30 disc d having a projection e upon its periphery, which, as the disc rotates successively engages insulating blocks 91 and 92 which respectively are secured to a contact of each of the pairs 89 and 90, and by such engagements operates to open the contacts. It will 35 now be seen that while the wires 86 and 87 are normally grounded, that at a certain point of the revolution of the disc d the pair of contacts corresponding to each of these 40 wires is opened and that the opening of the two pairs of contacts is successive, that pair which controls the connection of the relay R^{11} being opened first and after a short interval the contacts controlling the relay R^{12} 45 are opened, the contacts controlling one of the relays being closed when the other pair is open. The disc d is supposed to be rotating in the direction as indicated by the arrow.

Referring to the wires 82 and 83 hereinbefore mentioned as those over which the switch-actuating impulses are sent, the wire 50 82 is connected through a pair of contacts 93 with ground when these contacts are closed, these contacts however, being normally open. The wire 83 is multiplied into a contact of each of a plurality of relays R^{13} , R^{14} , R^{15} , R^{16} and R^{17} . Those contacts of the relays referred to which are 55 opposite those connected with the wire 83, are respectively multiplied with one contact of each pair of a row of push buttons or other suitably actuated contacts. Thus the contact 94' of the relay R^{13} is opposite and adapted to be brought into engagement with a contact 95' which is connected through a 60 wire 96' with one of each of the pairs of contacts in the row OK. Similarly a contact of relay R^{14} is multiplied with one terminal of each of the row OK' of pairs of contacts, a contact of the relay R^{15} is multiplied with 70 contacts of the row OK², a contact of the relay R^{16} is multiplied with contacts of the row OK³ while a contact of the relay R^{17} is multiplied with contacts in the row OK⁴. A contact of a pair in each of the rows OK, OK', 75 etc. is multiplied with the corresponding contacts in the other rows, these multiplied contacts being connected with a contact of one of the pairs of contacts 94, to 103 inclusive. Thus, a contact of the first pair at the 80 left in each of the rows OK, OK', etc. is connected with one contact of the pair 94. Similarly a contact in each of the pairs which are second from the left-hand end in each of the rows OK, OK' etc. is connected with a contact of the pair 95. Similarly contacts of the different rows are connected with contacts in the pairs 96 to 103 inclusive. The contacts of the pairs 94 to 103 inclusive which are not connected with the rows OK, OK', etc. as just described, are multiplied together and connected to one of the pair of contacts 104, the other one of that pair of contacts being connected to a 85 wire 105 connected with the free terminal of the battery B^3 . The contacts 104 are normally open but are closed at regularly recurring intervals by a disc d' having a corrugated or notched surface against which bears an insulating projection 106, this projection being secured to one of the contacts of the pair 104. It will now be seen that as the disc d' rotates battery connection will be thrown upon one contact of each of the pairs 94 to 103 inclusive. If one of these pairs is 90 closed, this battery connection will be thrown upon one of each of the contacts in the pairs of the rows OK to OK⁴ inclusive according to which one of the pairs 94 to 103 inclusive is closed. Battery having been thus thrown on one of the rows of contacts OK, OK', etc. this battery connection will be transmitted to the wire 83 which connects with the so-called vertical wire of the talking trunk, by 95 means of the contact of one of the relays R^{13} to R^{17} inclusive depending upon which one of these relays is energized. Each one of these relays has one terminal connected with ground as shown while the other terminal of each of the relays is respectively connected with a contact of one of the pairs 107 to 111 inclusive, the other one of these pairs of contacts being multiplied together and connected with the battery wire 105. 100

It will now be seen that each of the relays R^{13} to R^{17} inclusive are respectively controlled by the pairs of contacts 107 to 111 inclusive. Suitable means is provided for continuously rotating the disc d' , thereby 105 throwing battery upon one side of one of the 110

pairs of contacts 94 to 103 inclusive at regularly recurring intervals while the several pairs of contacts last referred to are each operated by means which holds them closed for an interval of time during a given number of makes of the contacts 104, this number of makes depending upon the particular pair of contacts. Thus, the pair 103 is held closed during one closure of the contacts 104, and the pair 103 is connected with push-button contacts at the extreme left of all the rows OK, OK', etc. Similarly the pair of contacts 102 is held closed during two closures of the contacts 104 and the pair 102 is connected with the pairs of contacts which are second from the left hand end in the rows OK, OK', etc. In like manner the pairs of contacts as they progress from the pair 102 to the pair 94 are held closed during progressively increasing intervals, each pair being held closed for a time of sufficiently greater length than the pair next preceding it, to permit one more closure of the contacts 104 during its closed period than took place during the closure of the said preceding pair. Thus, the contacts 101 are closed during three closures of the contacts 104, the contacts 100 are closed during four closures of the contacts 104, etc. It having been before noted that these pairs of contacts 103 to 94 are respectively connected to the several pairs of push button contacts in the rows OK, OK', etc., it will now be seen that if any particular button in one of these rows is depressed and its contacts closed, the particular pair of contacts in the group 103 to 94 will be connected with the common wire of the row. The common wires of the rows, as has before been noted, are respectively connected with contacts of the relays R¹³ to R¹⁷ inclusive, the connections of these common wires of the key rows with the wire 83 leading to the talking trunk being respectively controlled by the relays R¹³ to R¹⁷ inclusive. It has also been set forth that the relays R¹³ to R¹⁷ inclusive are respectively controlled by the pairs of contacts 107 to 111 inclusive. It will therefore appear that the connections of the push-button or key-rows OK, OK' etc. with the wire 83 are controlled by the operation of the contacts 107 to 111 inclusive. Means for operating these contacts is provided so that they are successively closed thereby causing the connection of the key-rows with the wire 83. Thus, assuming the row OK to be the thousands row, the row OK' to be the hundreds row etc., the pairs of contacts 107, 108, 109, 110 and 111 will be closed in the order named. The impulse sending apparatus is shown as arranged on the decimal system and there are therefore shown ten pairs of push-button contacts in each of the rows OK, OK', etc. The number of push-button rows OK, OK' etc. will be equal to the number of digits in the largest number of a subscriber's station which is to be called by the apparatus, and, as these numbers will depend upon the number of subscribers served the number of push-button rows will be supplied accordingly. Of course, there will be a relay such as one of the relays R¹³ to R¹⁷ inclusive to each push-button row OK, OK' etc. and corresponding to each of these relays will be a controlling pair of contacts as one of the pairs 107 to 111 inclusive.

The contacts 93, connected with the wire 82 which leads to the relay R⁵ of the talking trunk are adapted to be closed between the successive closings of the pairs of contacts 107 to 111 inclusive and thereby operate to send a rotary impulse over the talking trunk to the automatic selector or connector switches between the sending of the vertical impulses through the instrumentality of the push-buttons of the rows OK, OK', etc., the pairs of contacts 94 to 103 inclusive, the pairs of contacts 104, the pairs of contacts 107 to 111 inclusive and the relays R¹³ to R¹⁷ inclusive.

The contacts 93, connected with the wire 82 which leads to the relay R⁵ of the talking trunk are adapted to be closed between the successive closings of the pairs of contacts 107 to 111 inclusive and thereby operate to send a rotary impulse over the talking trunk to the automatic selector or connector switches between the sending of the vertical impulses through the instrumentality of the push-buttons of the rows OK, OK', etc., the pairs of contacts 94 to 103 inclusive, the pairs of contacts 104, the pairs of contacts 107 to 111 inclusive and the relays R¹³ to R¹⁷ inclusive.

I have hereinbefore mentioned Strowger automatic switches. This type of automatic switch has been chosen to illustrate the present invention, and, in the system shown, both Strowger selectors and connectors are employed, the construction of such switches being well shown in Letters Patent No. 815,176 and No. 815,321, granted to Keith and Erickson, March 13, 1906.

The trunk wires 61 and 62 extend as shown in Fig. 13 to the side switch arms s¹⁰ and s¹² of the selector switch S'. This switch is of the Strowger type above referred to and has a spindle arranged for both vertical and rotary movements, this spindle being placed at the axis of a set of contacts arranged in ten rows of ten each. Carried on the spindle are talking circuit wipers s¹⁶ which cooperate with the multiple bank contacts s¹⁸ and a test wiper s²⁰ which cooperates with the multiple test contacts s²². The switch spindle is stepped up to bring its wipers opposite the desired row of contacts by means of the so called vertical magnet v controlled through a relay V and the rotary movement of the switch is brought about by means of a vibrator magnet v' which makes and breaks its own circuit as it vibrates and is controlled by the relay T when the side switch arm s⁸ is in its second or intermediate position. Q is the release relay of the switch and q is the release magnet governed thereby. The other parts of the apparatus as well as the circuit connections will sufficiently appear from the statement of operation hereinafter. From the multiplied bank contacts s¹⁸, talking trunk conductors 112 and 113 extend to the switch arms s¹¹ and s¹³ of the side switches of a second selector switch S². This switch

and appurtenant apparatus is like that of the switch S' and comprises a vertical magnet v^2 , a rotary magnet v^3 , controlling magnets V and T' , a release relay Q' and a release magnet q' . The wipers s^{23} of the talking circuit engage with multiple bank contacts s^{24} while the test wiper s^{25} is adapted to engage with a multiple test contact s^{26} . S^3 designates a connector switch which is 5 designed to cooperate with the selector switch S^2 . It has a similar spindle carrying wipers s^{27} adapted to engage with multiplied bank contacts as s^{28} (see Fig. 8) connected to a subscriber's line. The test is made on 10 the tip or upper side of the line. This switch also contains line contacts in its banks arranged in rows of ten each. The spindle is stepped up to bring the wipers s^{27} opposite the desired row by means of a so 15 called vertical magnet v^4 and is rotated step by step by means of a so called rotary magnet v^5 , which in this case is not a vibrator but responds to distinctive current impulses, since the desired line is identified with a 20 single pair of contacts only, and therefore the row of contacts must be selected and the pair of contacts in the row afterward picked out by the wipers, before testing. In this 25 resides the principal difference between the connector and selector switches, the purpose 30 of the selector switch being to pick out and connect with an idle trunk line in any desired group. In the operation of the selector switch, therefore, the spindle is stepped up by means of definite and distinctive 35 impulses to the row of contacts representing the desired group (which may be either thousands or hundreds, it being thousands in the case of the switch S' and hundreds in 40 the case of the switch S^2), and after that when the side switch has taken one step, the rotary magnet takes control of the switch and steps the spindle around continuously as long as the test wiper finds ground on 45 its cooperating bank contacts. When this ground fails (the busy contacts being grounded and the idle one open) it means that an idle contact has been reached, and thereupon the side switch is moved a second 50 step to cut off the rotary magnet and stop the wipers upon this ungrounded or idle contact.

The connector circuit shown in Fig. 14 55 contains a pair of condensers K^2 and K^3 for the reason that the forward impulses which work the switch must not be confused by the battery current supplied to the called subscriber. The condensers just referred to are interposed between the talking trunk 60 conductors 114 and 115 on the one hand and the talking trunk conductors 116 and 117 on the other, the conductors 114 and 115 extending from the bank contacts s^{24} of the selector switch S^2 and the conductors 116 65 and 117 extending forward into connection

with the side switch arms s^{29} and s^{30} of the connector switch S^3 . For the purpose of supplying talking current to the called subscriber, a battery as B^4 , is connected to the sleeve conductor 117 of the connector switch 70 through the relay R^{18} and the tip conductor 116 is grounded through the relay R^{19} which is the same as connecting it back to the battery. Thus, the battery is bridged across 75 the conductors 116 and 117 through the relays R^{18} and R^{19} which are wound so as to present high reactance to voice currents. R^{20} is the ringing relay which controls the application of the ringing current to the 80 called line and is itself controlled on the one hand by the relay R^{19} and on the other by a commutator I^2 which may be common to all the ringing relays of the exchange. The circuit of the ringing relay terminates, at 85 the commutator end in ground and at the other end at the free terminal of the battery. This circuit is controlled by the relay R^{18} and the latter relay does not become energized until the side switch arms s^{28} , s^{29} , s^{30} and s^{31} have made their last step so that 90 the conductors 116 and 117 are connected to the wipers s^{27} . Before this last step of the side switches is taken the wipers s^{27} have been placed upon the terminals of the called line and the release relay Q^2 has been applied to the tip side of the line for the 95 purpose of testing it. When the line is busy battery is connected to the tip side either by the way of relay or prime Fig. 12 or relay R^{18} Fig. 14. This battery supply flows 100 to the tip side of the line through the subscriber's telephone set when his receiver is removed from the hook. The test or release relay Q^2 will then receive current, but if there is no battery because the line wanted 105 is idle then the test relay remains unaffected, the talking circuit is completed and the sleeve relay R^{18} becomes energized by the current passing to one of the wipers s^{27} and thence through one of the multiple contacts (Fig. 8) and the cut-off relay as M^2 110 to ground. The cut-off relay thereupon pulls up and the ringing relay circuit is at the same time completed so that the commutator I^2 takes control thereof. It will 115 be observed that this ringing relay circuit passes through a back contact of the relay R^{19} and through a forward contact of the relay R^{18} so that it is necessary to a completion 120 of this circuit that the relay R^{19} shall be deenergized and the relay R^{18} shall be energized. It will now be apparent that as soon as connection with the wanted subscriber 125 has been established the relay R^{18} will pull up while the relay R^{19} will not pull up until the called subscriber removes his receiver from its hook, the relay R^{19} being controlled by the called subscriber in the intervals of ringing, for it will be observed that the 130 commutator I^2 has segments whereby it

closes the ringing circuit at intervals only. While this circuit is open and the relay R^{20} deenergized in consequence, the taking down of the called subscriber's receiver operates to energize the relay R^{19} whereupon the ringing relay circuit is broken. It will now appear that the ringing apparatus is connected up with the called subscriber and operates to ring intermittently until the subscriber answers when the ringing apparatus is disconnected by the breaking of the ringing relay circuit as just described. In order that the relay R^{18} may remain energized through the ringing intervals, a special battery connection is provided as shown.

The relay R^{21} controls the release relay Q^2 the circuit of which passes through a front contact of the relay R^{21} and a back contact of the relay R^{19} . It is therefore apparent that a closing of the circuit of the release relay is effected when the relay R^{21} is energized and the relay R^{19} is deenergized. One terminal of the relay R^{21} is connected with ground while the other is connected through a front contact of the relay R^{19} with a battery connection made through contacts under the foot of the spindle of the connector switch S^3 . These contacts tend to come into engagement but are held apart by the switch spindle when the switch is in its zero or normal position. The relay R^{21} may also have the circuit of its magnet locked upon the battery connection just described by a front contact of one of its own armatures. Whether the circuit of the relay R^{21} is made through the contacts of the relay R^{19} or its own contact however, the battery connection is controlled by the contacts under the switch spindle. It has before been set forth that the relay R^{19} will become energized on the taking down of the receiver of the called subscriber and, upon this energization, the circuit of the relay R^{21} will be initially closed. The relays R^{19} and R^{21} will then both be energized which is not the condition for closing the circuit of the release relay Q^2 . Battery will be locked upon the relay R^{21} until the connection is broken at the contacts under the switch spindle upon its return to its initial or zero position. Upon the hanging up of the subscriber's receiver, the relay R^{19} will be deenergized but the relay R^{21} will remain energized until its circuit is broken at the contact under the spindle S^3 which will not occur until the switch spindle has been restored. Between the hanging up of the called subscriber's receiver and the return of the switch S^3 to its zero position, the conditions will be such that the circuit of the release relay Q^2 will be completed and the switch S^3 will be released and will return to its normal position. It is unnecessary to give here any further description of the cir-

cuits and apparatus of Fig. 13 or of the connector circuit thus far described and shown in Fig. 14, all of these being old and well-known to those skilled in the art while their relation to the present system and their manner of operation in conjunction therewith will sufficiently appear from the statement of operation hereinafter.

The arrangement of switches shown in Figs. 13 and 14 is sufficient for exchanges up to ten thousand lines capacity, but in order to provide for more than ten thousand lines another set of selector switches is required, interposed between the trunk ends of Fig. 12 and the switch S' of Fig. 13. The capacity of the exchange can be increased indefinitely without altering these circuits by adding these sets or groups of switches in the well understood manner. The selector switches all have the same circuits as those shown in connection with switches S' and S^2 and therefore I have considered it unnecessary to multiply illustration by showing more. It is within the power and skill of every person having a fair knowledge of the automatic art to add as many sets of selectors as may be desired. Regardless of the number of switches, the method of operation is to send the selecting or working impulses over the talking trunk wire 61 which is commonly called the vertical wire, and to send the controlling impulses over the trunk wire 62 which is commonly called the rotary wire. The so called rotary impulses serve to work the side switch magnets T , T' and T^2 , and thereby to shift the said switches so as to bring into play successively the vertical and rotary magnets, the test relay etc.

If each of the subscribers' lines served but a single subscriber it would be sufficient for ringing purposes to connect any suitable source of ringing current between the contacts 120 and 121 and then when the relay R^{20} is energized the connection between the trunk wires 116 and 117 on the one hand and the wires extending forward to the connector switch on the other would be broken apart and the wires extending to the connector switch would be connected to the terminals of the source of ringing current. In the systems shown in the drawings however, provision is made for selectively ringing any one of a plurality of subscribers connected to a common line. The specific number of subscribers upon a party line which is provided for in the apparatus shown, is four, but obviously the apparatus herein may be extended to accommodate any number desired upon a party line. The selective ringing apparatus referred to is shown in Fig. 15. It comprises a plurality of generators U , U' , U^2 and U^3 of different frequencies through which the ringing circuit of a called subscriber may be made.

The ringing apparatus of each of the several subscribers upon a party line is attuned to operation by current impulses of a frequency corresponding to one of the generators 5 to U to U^3 and is operable only by current transmitted by the particular generator to which it is attuned. Thus, the armature of the bell magnet, at a subscriber's station may be so constructed as to have a natural 10 period of vibration corresponding to one of the generators. It will then be operated only by that generator and similarly, the periods of vibration of the bell armatures of the other subscribers upon the party line 15 being adjusted to other periods of vibration, any of the subscribers of the line may be rung up to the exclusion of the others by connecting the proper generator to the line. The selection of the generator to be connected in the ringing circuit is controlled 20 by the operator by means of impulses sent over the tip-side of a talking trunk and through the relay V^2 which, at each energization throws a ground connection upon 25 the relay R^{22} through the wire 122 and the side switch arm s^{28} when the latter is in its last position. At each energization and de-energization of the relay R^{22} , a magnet of 30 the series R^{23} to R^{28} inclusive is energized and the two magnets energized by the energization and deenergization consequent upon 35 one impulse results in the connecting of a particular generator into the calling circuit. Thus, a single impulse causes the energization of the relays R^{23} and R^{24} whereby the connecting of the generator U in the calling circuit is effected. The relays R^{23} and R^{24} having been once energized, a battery connection is locked on them and they each have 40 one terminal connected with ground. The battery connection referred to is made through the wire 123 and is controlled by the relay R^{18} which operates to close this connection when the wipers of the connector switch S^3 rest upon the wanted subscriber's 45 line. The connecting of the generator U in circuit also operates to disconnect the generator U' which is normally in circuit and would transmit the current impulses if no 50 impulses were caused by the operator to pass through the relay R^{22} . Upon a second impulse through the relay R^{22} the generator U would be disconnected and the generator U^2 would be connected in the ringing 55 circuit. Similarly a third impulse through the relay R^{22} would cause the disconnection of the generator U^2 and the connection of the generator U^3 into the ringing circuit. The connection of the circuit through the generator selected, with the subscriber's line is effected through the wire 124 which is connected with the contact 120 which, as has before been seen is thrown into connection with its respective wiper s^{27} by the energization 60 of the relay R^{20} . The other wiper of the pair s^{27} is connected with the contact 121 which is connected with the other terminal of the source of ringing current. The impulses for selecting the generator to be connected in the ringing circuit are controlled 70 by means of the keys or push buttons in the row OK^4 of the operator's set (see Fig. 19).

Referring to Figs. 5 and 6 there is shown therein a concrete embodiment of apparatus 75 comprising contacts corresponding to the contact 89, 90, 93, 94 to 104 inclusive, and 107 to 111 inclusive as shown in Fig. 19 and, in addition to these contacts, provided with means for operating these 80 contacts in the manner and order described. There is also embodied in this machine contacts and operating means for performing the function of the interrupter I^2 (see Fig. 14). The apparatus shown in Figs. 5 and 85 6 comprises standards g and h in which is rotatably mounted a shaft i . To this is fixed a worm wheel j which engages with a worm k rotatably mounted upon the standard h . Also secured upon the shaft i is a 90 drum l , the surface of which is of such conformation as to suitably operate contacts which are mounted adjacent its surface. In the present instance the contacts operated by the drum are mounted upon a bar or 95 plate m which extends longitudinally over the surface of the drum and is supported by arms n and o which extend from the supports g and h . Each of the pairs of contacts (see Fig. 5 particularly) comprises 100 two contacts p and t which are located one above the other and which are so mounted as to be insulated from each other. The contact p is maintained in elevated position by means of a button u which rests upon the plate m and, passing through the lower contact t abuts against the lower side of the contact p . The lower contact t tends to occupy its lowest position but may be moved upwardly into engagement with the 105 contact p by means of an insulating button w which is adapted to abut against the lower side of the contact t and, passing through the plate m , its lower end is adapted to be engaged by the drum so that when an elevated portion of the drum is encountered the button will be raised and the contact t thrown against the contact p and conversely a less elevated portion of the drum will permit the button to fall and the contacts 110 p and t to separate. The buttons v and w are and act as insulating studs or separators as in ordinary relays for operating and spacing the contact springs. In the apparatus of Figs. 5 and 6 the pair of contacts 104' 115 correspond to the contacts 104 of Fig. 19. Similarly the pairs of contacts 89' and 90' correspond to the pairs of contacts 89 and 90, the contacts 93' correspond to the pair 93, the contacts 107' to 111' inclusive cor- 120 125 130

respond to the contacts 107 to 111 inclusive and the contacts 94' to 103' correspond to the contacts 94 to 103 inclusive, while the contacts 130 and their cooperating section 5 of the drum perform the function of the interrupter I². At the extreme left-hand of the drum (see Fig. 6) are arranged equally spaced elevations 131 so that as the drum turns the pair of contacts 104' will be 10 moved into and out of contact at equally recurring intervals. Referring now to the other end of the drum it will be seen that there are triangular shaped elevations 132, the angular edges of which are saw-toothed 15 so that the successive sections of the drum upon which the buttons of the contacts 94', 95' etc. bear as the drum turns, are of progressively increasing lengths so that the button of the contact 94' will be elevated and 20 therefore its contacts held in engagement for a certain interval, the button of the contacts 95' will be elevated for a greater interval, the button of the contacts 96' will be elevated for a still greater interval and 25 so on to the button of the contacts 103' which is held elevated for the longest interval. Those elevations on the drum section over which the button corresponding to the contacts 94' passes, are of such length 30 that the button will be maintained elevated and its contacts closed, while the contacts 104' are made once. Similarly the contacts 95' are held closed while the contacts 104' are made twice and so on to the contacts 35 103' the button of which is held elevated while the contacts 104' are made ten times. In order to avoid the breaking of current 40 upon other contacts than the pair 104' it is preferred to make the elevations operating the contacts 94' to 103' of such lengths that 45 their respective buttons will pass off those elevations just after the button corresponding to the contacts 104' has passed off an elevation. This will avoid arcing at other contacts than 104' and will do away with the necessity for renewal of any other contacts except under extraordinary circumstances.

Arranged alongside the elevations 132 are 50 the elevations 133, 134 etc. which are circumferentially coextensive with their respective elevations 132 and are displaced longitudinally upon the drum so that during the passage of an elevation 132 under the contact buttons, the corresponding elevation 133, 134 or the like will be passing under one of the buttons 107' to 111'. Thus, during the passage of the elevation 132 which is shown at the top of the drawing in Fig. 6, the elevation 133 will maintain the button of the contacts 111' elevated and those contacts closed. During the passage of the next elevation 132, the elevation 134 will hold the button of the contacts 110' uplifted and those contacts closed. Similarly other elevations of the

same nature as 133 and 134 will maintain the contacts 107', 108' and 109' closed during the passage of their corresponding elevations 132.

It will now be apparent from a comparison of the description of the apparatus shown in Fig. 6 and the diagram of Fig. 19 and the description thereof that there is an elevation 132 corresponding to each of the rows of push buttons OK to OK⁴ and that these elevations operate to throw the proper number of impulses upon the respective push buttons of a row while the contacts 104' and their cooperating elevations upon the drum serve to produce the impulses which are selectively applied to the push buttons by the elevations 132 and their cooperating contacts, the application of the impulses thrown upon the push buttons to the automatic switches being controlled by the manipulation of the push buttons by the operator.

It has been before set forth that the different rows of push buttons OK, OK' are successively connected with the wire leading to the talking trunk and automatic switches by means of the relays R¹³, R¹⁴, etc. It is to successively energize these relays that the elevations 133, 134, etc. and their cooperating contacts are provided. Thus, the elevation 133 closes the contacts 111' which makes the circuit for the relay which connects in the thousands row of push buttons and maintains the contacts 111' closed while the appropriate number of impulses are applied to each one of the push buttons in the row. The elevation 134 acting upon the contacts 110', performs a similar function in regard to the hundreds row of push buttons and so on, as many elevations 132 and corresponding elevations 133, 134, etc. being provided as there are rows of push buttons in the operator's key-set.

It is the common practice in operating automatic telephone switches to operate those switches by a plurality of series of so called vertical impulses, a single so called rotary impulse being transmitted between succeeding series of vertical impulses. This feature of operation is employed in the apparatus illustrated and has been referred to hereinbefore. To supply these rotary impulses elevations 135, 135 etc. are provided upon the drum, these elevations being adapted to elevate the buttons of the contacts 93' and close those contacts. It will be noted that these elevations 135 and 136 are placed circumferentially between the elevations 132, 133, 134 etc., which are concerned in the sending of vertical impulses, so that between the termination of the application of current impulses to one row of push buttons and the commencement of the application of similar impulses to the next row of push buttons the contacts 93' will have their button elevated and will be closed. This results in the send-

ing of a rotary impulse to the automatic switches as before referred to.

The drum l is preferably continuously rotated, and, this being the case, the operation would be confused if the operator should set up a number on her rows of push buttons or key-set while the drum was in an intermediate position and the transmission of impulses to the automatic switches should 10 be immediately begun, thus, at the time the operator depressed her buttons, the elevations on the drum corresponding to the thousands row or the hundreds row or both might have already passed under the contacts and 15 would not do so again until the next revolution. Without means to prevent such a happening therefore, the sending of the impulses might begin with the hundreds contacts and succeeding impulses would follow 20 until at the beginning of the next revolution the thousands and hundreds impulses would be sent. The confusion which would result is obvious. In order to avoid this confusion means is provided for causing the 25 commencement of the sending of impulses with the beginning of a revolution of the drum so that all the impulses will be sent in their proper order. This means has been hereinbefore referred to in connection with 30 the diagram shown in Figs. 18 and 19 as the contacts 89, and 90 operated by the disc d and controlling the relays R^{11} and R^{12} . A mechanical arrangement of these contacts however, which it is preferred to use is 35 shown in Fig. 6 and consists in the pairs of contacts 89' and 90' the buttons of which ride upon an elevation 136' throughout the entire revolution of the drum except for two depressions 137 and 138 into which the buttons 40 are respectively adapted to drop. When the buttons are elevated their cooperating contacts are closed and therefore the contacts 89' and 90' are always closed except for the short intervals during which the buttons 45 corresponding to these contacts rest in the depressions 137 and 138. It will be noted that the depression 138 is slightly in advance of the depression 137, the drum rotating in the direction as indicated by the 50 arrows, so that the contacts 90' are first opened and then the contacts 89'. The pairs of contacts 89' and 90' operating to initiate the calling operation after an operator has set up a number on her key-set, it is to be 55 observed that the depressions just referred to circumferentially precede elevation 133 and its corresponding elevation 132 which control the application of impulses to the thousands row of push buttons so that the sending 60 of a set of impulses for operating the automatic switches of a trunk are always initiated with the thousands apparatus.

The interrupter I^2 (see Fig. 14) for controlling the ringing as has been before referred to is mechanically embodied in the

structure shown in Figs. 5 and 6 by means of the contacts 130 the button of which is held raised during half or other suitable fraction of a revolution by means of an elevation 138' upon the drum l , the button during the remainder of the revolution traversing a depression 139 when the contacts 130 are open. It will readily be understood that the machine shown in Figs. 5 and 6 may serve a plurality of operators' equipments and 70 in fact it will probably never be found necessary to have more than one of these machines in an exchange, and the same contacts or contact in this machine may often perform a plurality of functions. Thus the 75 contacts 130 may perform the function of an interrupter for other circuits than the ringing relay as well as for that circuit and for instance it might also perform the functions of the interrupter I (see Fig. 8), and 80 also of the interrupter for the secondary distributing switch SDS (see Fig. 16). The manner of connecting the machine shown in Figs. 5 and 6 to a plurality of operators' 85 equipments is indicated in Fig. 19 where it 90 will be understood that those wires shown as ending in arrow heads are respectively continued to those portions of other operators' equipments corresponding to those to which these wires are connected in the equipment shown. 95

Having set forth apparatus by means of which my invention can be carried out, its operation as a whole and the relations of the various portions to each other can be best 100 set forth by tracing the connections effected and operations performed from the initiation of a call by a subscriber until the connections have been completed between the 105 calling and wanted subscribers, the conversation completed and the apparatus restored or cleared out.

Let it be assumed that the subscriber at a station as A desires to converse with a subscriber at some other station. When 110 the subscriber removes his receiver and therefore permits the receiver hook to rise in the usual manner circuit will be completed from the battery wire 5 (see Fig. 8) through the magnet of the line relay N^a , the armature m^a of the cut-off relay M^a , conductor 1 of the subscriber's line, the subscriber's instrument, the conductor 2 of subscriber's line, and the armature m'^a of the cut-off relay to ground. The energization of the line 115 relay N^a by reason of the completing of the circuit just traced results in the attraction of its armature when the conductor 7 will be connected by the armature n^a with the battery wire, the conductor 8 of the group D will be connected through the armature N'^a to the battery wire and the wire 6 leading to the primary distributing switch PDS 120 will be connected through the armature n''^a with the battery wire. The circuit of the 125

magnet of the primary distributing switch is then completed from the battery wire 5 through the armature n''^a , conductor 6, the coil of the magnet, and the interrupter I to ground. The magnet will thus be intermittently energized as the interrupter rotates and the movable member of the switch will be stepped forward. From the position shown one of the arms of the movable member will first come in contact with the left-hand one of the contacts c , this contact being connected with one terminal of the trunk distributing relay TR. It is assumed however, that the trunk corresponding to this relay is busy and therefore the wire 140 which extends from one terminal of the relay and is connected to a wire as 70 (see Fig. 12) would have its ground connection opened at an armature as 3' of the sleeve relay R', the sleeve relay being energized when the trunk is in use. This condition of affairs existing, the arm of the movable member of the primary distributing switch will pass on to the next one of the contacts c , which contact is connected with one terminal of the trunk distributing relay TR' and which it will be supposed, corresponds to an idle trunk. This being the case the conductor 70 will have a ground connection established through the armature 3' of the sleeve relay of the trunk. Circuit may be thereupon traced from the battery wire 5 through the armature n''^a of the line relay, conductor 6, the movable member of the primary distributing switch, the second one from the left of the contacts c , conductor 141, the magnet of the relay TR', conductor 70, and the armature 3' of the sleeve relay of the trunk to ground. Circuit being thus completed through the trunk distributing relay TR', its armature will be attracted and the contacts upon one side which are connected with the group D of conductors will be connected with the contacts on the other side which are connected with the group E' of conductors. It has before been noted that the energization of the line relay has placed battery connections on the wires 7 and 8 of the group D. These particular conductors of the group D are respectively connected with the contacts 9' and 10' of the trunk distributing relay, which contacts are opposite the contacts 50 and 51 and with which they are adapted to engage when the relay is energized. The contacts 50 and 51 respectively are connected with the conductors 11 and 12 of the group E' and it will now be observed that the energizing of the relay has operated to connect the conductors 7 and 8 with the conductors 11 and 12, thereby throwing battery upon these latter conductors. Tracing the course of the wires 11 and 12 into the apparatus shown in Fig. 9, it will be seen that the wire 11 is connected with one terminal of the

magnet of the units relay PUR⁷, and that the wire 12 is connected with one terminal of the tens relay PTR³. Circuit may now be traced from the battery wire 5 through the relay armature n''^a , conductor 8, contacts 9' 70 and 51, conductor 11, and the magnet of the units relay PUR⁷, to ground. Another circuit may be traced from the battery wire 5 through the armature n''^a , conductor 7, contacts 10' and 50, conductor 12 and the magnet of the relay PTR³ to ground. The relays PTR³ and PUR⁷ will thus become energized and will close their contacts. The closing of the contacts of the tens relay PTR³ will throw all of its contacts on the one side which are connected with the conductors of the group MT with its contacts on the other side which are connected with the conductors of the other group MT^b. In the group of wires MT so connected, are the wires 20 and 13 connected with the contacts 17 and 14 of the relay. The conductors 20 and 13 have connected to them the conductors 3 and 4 which serve to extend the subscriber's line when the cut-off relay M^a is 80 closed. The particular contacts 1' and 14 which correspond to the calling subscriber are, when the tens relay is closed, connected with the particular conductors 30 and 31 of the group MT^b. These particular conductors of the group MT^b are connected by means of the conductors 28 and 29 with the contacts 25 and 27 of the units relay PUR⁷ which contacts when the relay is closed, come into engagement with the contacts 26 95 and 28 which are connected to the conductors 38 and 40 and thence to the talking trunk conductors 39 and 41. It will now be apparent that although a considerable number of pairs of the conductors constituting the group MT were connected with the group MT^b and therefore, that a plurality of line connections were partially formed with the talking trunk by the closing of the tens relay, only one pair of the conductors MT^b, 100 and that pair corresponding to the line of the particular calling subscriber, has its connection completed with the talking trunk. The lines 3 and 4 having been thus extended to the conductors of the talking trunk, circuit may be traced from the ground through the cut-off relay M^a, conductor 4, conductor 13, contacts 14 of the tens relay PTR³ and its cooperating contact, conductor 31, conductor 29, contacts 27 and 28, conductor 40, 105 conductor 41, and the sleeve relay R' to the battery wire 52. The cut-off relay being thus energized, it attracts its armatures thereby breaking the circuit of the line relay N^a at the armature m''^a while the subscribers' line conductors 1 and 2 are connected with the wires 3 and 4 by the armatures m''^a and m''^a . The subscriber's line 2 being connected to the conductor 4, its connection 110 may be traced to the sleeve side 41 of the 115 120 125 130

talking trunk as before. Similarly circuit may be traced from the subscriber's line conductor 1 through the armature m^a , conductor 3, conductor 20, contact 17, conductor 6 30, contacts 25 and 26, and conductor 38 to the tip-side 39 of the talking trunk. It will now be seen that both of the subscribers' lines 1 and 2 are connected with their respective sides of the talking trunk. It will also 16 be noted that the sleeve relay R' , being connected in series with the cut-off relay M^a is energized at the same time with that relay.

The energization of the cut-off relay resulting in the deenergization of the line relay N^a , causes battery connections to be 15 broken at its armature n^a , n'^a and n''^a . This removes battery from the tens relay PTR³ and the units relay PUR⁷, it also removes battery connection from the primary distributing switch PDS. The removal of this battery connection from the distributing switch results in the stopping of the movable member. From the time a terminal of a trunk distributing switch magnet is contacted with 20 until the line relay is deenergized, such a short interval of time elapses that the movable member of the switch will be arrested before it has time to proceed to the contact corresponding to the next trunk distributing 25 relay. The removal of the battery connections through the relays n^a , and n'^a from the tens and units relays would result in the deenergizing of those relays and the breaking of the connection of the subscriber's line 30 with the talking trunk wires if some other means were not provided for maintaining the battery connections of these relays. Such maintenance of the battery connections is provided by means of the contact 49 35 and its cooperating contact in the tens relay and the contacts 45 and 46 in the units relay. When the relays are closed circuit may be traced from the ground side of the magnet of the tens relay through the contact 49, 40 its cooperating contact, the conductor 48, and the armature r^2 of the relay R^2 to the battery wire 52. Circuit may also be traced from the ground side of the units relay through the contacts 45 and 46, and the 45 wire 47, to the wire 48 which is connected with battery as described. It will thus be seen that immediately that connection is formed with a talking trunk, battery connections will be locked on the closed tens 50 and units relays through their own contacts and these relays thus remain energized on the breaking of their initial battery connections at the armatures n^a and n'^a of the line relay. The energization of the relay R' 55 as described and the consequent attractions of its armatures results in the breaking of the ground connection of the wire 70 at the armature 3^r so that as before referred to it will be impossible for the primary distributing switch to complete a circuit through the

trunk distributing relay while its corresponding trunk is busy.

Immediately that the talking trunk wires 39 and 41 are connected with the subscribers' line wires 1 and 2 as before described 70 the relay R becomes energized, a circuit being traceable from the grounded side of the magnet of the relay R through the coil of that magnet to the talking trunk wire 39 thence by circuit as before traced to the 75 subscriber's line 1, thence through the subscriber's instrument to line 2, and thence by connections before traced to the talking trunk wire 41 and thence through the relay R' to the battery wire 52. The attraction of 80 the armature r of the tip relay R establishes a battery connection for the wire 48 and thereby maintains the battery connection of the tens and units relays when the relay R^2 shall have become energized. The attraction 85 of the armatures 1^r and 2^r result in the breaking of the connections of the wire 142 with both the tip and sleeve sides of the trunk, the wire 142 being connected with battery when the relay R^2 is energized. It 90 will therefore be seen that when the relay R^2 is energized and the tip relay R is deenergized that battery will be thrown onto both sides of the talking trunk.

The sleeve relay R' being energized, circuit may be traced from the battery wire 52 through the armature r' , conductor 143, armature 2^{r^2} , and conductor 57 which is connected with the wire 58 which multiples the 95 wire 57 with the corresponding wires of the other trunks. From the wire 58, the wire 57 passes on to one terminal of the magnet 100 of the secondary distributing switch (see Fig. 16) and also to the movable member 105 of that switch. The movable member of that switch is then stepped forward precisely as in the case of the primary distributing switch and it will be assumed that the operator's set corresponding to the secondary distributing relay SDR and which is connected with the first one of the stationary contacts of the secondary distributing switch, is idle. The movable arm of the distributing switch having come upon the contact corresponding to this relay, circuit may be traced from the wire 57 through the distributing switch, conductor 144, the magnet 110 of the relay SDR, the conductor 75 and the armature 1^{r^2} of the relay R^2 (see Fig. 17). Relay SDR will then be energized and its contacts will be closed. The relay R' of the talking trunk is also energized and therefore a battery connection is thrown on each of the wires 53 and 54 by the armatures 1^r , 2^r , r^2 and 1^{r^2} and therefore battery is 115 thrown on the contacts of the secondary distributing relay to which the wires 53 and 54 are connected. The contacts 145 and 146 to which these wires are connected are 120 respectively connected by the wires 147 and 130

148 with one terminal of each of the magnets of the tens relay STR^2 and the units relay SUR^0 , the other terminals of those relays being grounded. The tens and units relays referred to are therefore energized when the wire 63 will be connected through the contacts 147 and 148 of the tens relay and the contacts 149 and 150 of the units relay with the wire 71 which continues through the apparatus shown in Fig. 17 to the spring contact j^c of the jack J. The wire 64 is connected through the contacts 151 and 152 of the tens relay and the contacts 153 and 154 of the units relay with the wire 72 which leads through the apparatus of Fig. 17 to the contact j^b of the jack J. To the wire 72 (see Fig. 17) is connected the armature r^0 of the relay R^0 , a back contact of which is connected with one terminal of the relay R^8 , the other terminal of that relay being connected with ground. Circuit may now be traced from ground through the relay R^8 , armature r^0 , conductor 72, contacts 153 and 154, contacts 152 and 151, conductor 64, and relay R^5 to battery. The relay R^8 being thus energized, attracts its armatures whereupon circuit may be traced from the battery through the armature r^8 and the relay R^7 to ground. The armatures of the relay R^7 being attracted the ground connection of the magnet of the secondary distributing relay is broken between the armature 1^{r7} and the conductor 75 whereupon the contacts of that relay are open thus removing the battery connections through the wires 53 and 54 from the tens and units relays. The tens and units relays STR^2 and SUR^0 being closed however, circuit may be traced through the magnet of the relay SUR^0 , the contacts 155 and 156 of that relay and conductor 73 to conductor 74. Similarly circuit may be traced through the magnet of the tens relay STR^2 and the contacts 157 and 158 of that relay and the conductor 72' to the conductor 74, the conductor 74 being connected to a front contact of the armature 1^{r8} of the relay R^8 , this armature being connected with ground. Thus, it will be seen that the battery connections are maintained on the tens and units relays even though those connections through the conductors 53 and 54 are broken at the contacts of the secondary distributing relay, it being observed that the relay R^8 is energized before the secondary distributing relay is deenergized. Another result of the energizing of the relay R^8 is the connecting of one terminal of the signal lamp L with battery through the armature 2^{r8} . The other terminal of the lamp is grounded so that the lamp lights and attracts the attention of the operator. The energization of the relay R^5 in series with the relay R^8 and the resulting attraction of its armatures causes battery to be thrown upon one terminal of the relay R^5 through

the armature 2^{r5} and the conductor 159, whence the circuit passes through the relays R^3 and R^2 to ground. The attraction of the armature of the relay R^2 operates to throw battery upon the armatures 1^r and 2^r but these armatures are now attracted and hence are not in connection with the wires of the talking trunk. The attraction of the armatures of the relay R^3 results in the breaking of the battery connection to the wires 53 and 54 at the armature r^3 and 1^{r3} , while the attraction of the armature 2^{r3} breaks the battery connection of the wire 57 and forms a locking battery connection for its own magnet through the conductor 143 and the armature r' of the relay R' . The breaking of the battery connection through the wire 57 breaks the circuit to the secondary distributing switch and this switch stops, the operation necessary to bring about this result being so quickly performed that the movable member of the switch, after it comes into engagement with the secondary distributing relay of an idle operator's set, is stopped before it can move into contact with another distributing relay.

The attention of the operator having been attracted by the lighting of the lamp L, she inserts her plug P (see Fig. 18) into the jack J when the contacts p^c , p^b and p^a , will respectively engage with the jack contacts j^c , j^b , and j^a . Circuit may now be traced from battery in Fig. 17 through the relay R^0 , sleeve contact j^a of the jack, contact p^a of the plug (see Fig. 18) conductor 78, conductor 160 and the armature 3^{r11} of the relay R^{11} to ground. The relay R^0 being thus energized the circuit of the relays R^8 and R^5 is broken whereupon the lamp L is extinguished, the ground connection of the wire 74 is broken at the armature 1^{r8} but this connection is now maintained by the armature 2^{r8} . The battery connection of the relay R^7 is also broken at the armature r^8 but this connection is locked on the relay R^7 by means of the armature r^7 and the armature 1^{r9} of the now excited relay R^9 .

The operator having inserted her plug she now places herself in conversational communication with the calling subscriber by pressing the listening key LK. When this key is closed circuit may be traced from the battery B^2 through the relay R^{10} , conductor 79 and a listening key LK to ground. The energization of the relay R^{10} causes the connection of the conductor 77 through the armature r^{10} with the conductor 80 which is connected with one terminal of the operator's telephone and also the connection of the wire 76 through the armature 1^{r10} with the conductor 81 which is connected with the other terminal of the operator's telephone. The operator's telephone being thus connected across the line, circuit may be traced from the ground (see Fig. 12) 130

through the magnet of the relay R^4 and thus through the conductor 63 and connections as before traced to the conductor 76 (see Fig. 18) thence through the armature 1^{r10} , conductor 81, operator's telephone, conductor 80, and armature r^{10} to conductor 77 and thence through connections as before traced to the conductor 64 and the magnet of the relay R^5 (see Fig. 12) to battery. The relays R^4 and R^5 being thus simultaneously energized circuit may be traced from one terminal of the battery B' through the armatures 1^{r5} and 1^{r4} and the conductor 163 and the magnet of the relay R^6 to ground. The relay R^6 being energized, the conductors 67 and 68 which are respectively extensions of the conductors 63 and 64 will be respectively connected through the armature r^6 and 1^{r6} with the conductors 59 and 60 of the talking trunk. The subscriber's line having been connected with the talking trunk as before described, the operator's telephone is now in talking communication with the subscriber's instrument.

The operator having learned from the calling subscriber the number of the subscriber wanted, this number is set upon the operator's key-set (see Fig. 19) by depressing the proper buttons. Let it be assumed that the number wanted is 4,628-1, it being assumed that one of the subscribers on a party line is wanted, the final numeral corresponding to his number on the party line. The operator will then press the 4th button from the last in the row OK, the 6th button in the row OK', the 2d button in the row OK², the 8th button in the row OK³, and the 1st button in the row OK⁴, this last row containing the buttons for selectively calling the subscribers on the party lines, provision being made for four subscribers upon a line. There being four other rows by which lines are selected, it will be apparent that impulses for selecting lines up to ten thousand are provided for. It will be observed that by adding other rows of buttons to the key-set that any number of subscribers might be provided for.

The operator having set up the wanted subscriber's number on the key-set as described she then presses her starting key SK. Circuit may then be traced from the battery wire (see Fig. 18) through the relay R^{12} , conductor 84 and the starting key to ground. The energization of the relay R^{12} throws ground connection on the relay R^{11} through the armature 3^{r12} , the other terminal of that relay being connected with battery wire 85. The energization of the relay R^{11} brings the armatures r^{11} and 1^{r11} into contact with the conductors 164 and 165 which are adapted to be connected with the wires 82, and 83, over which the rotary and vertical switch actuating impulses are sent, by the armatures r^{12} and 1^{r12} . The last mentioned armatures however, are attracted at the stage of the operation which has been reached and therefore the attraction of the armatures r^{11} and 1^{r11} , to which the conductors 76 and 77 are connected, will not result in the connection of those conductors with the conductors 82 and 83. It will be observed that the connection between the conductors 76 and 77 on the one hand and the conductors 82 and 83 on the other, will be accomplished only when the relay R^{12} is deenergized and the relay R^{11} is energized. Both of these relays are energized at the stage of operation which has been reached. The relays R^{11} and R^{12} having been energized, ground connection will be locked on the relay R^{12} through the armature 2^{r12} , the conductor 86, and the contacts 89, while ground will be locked upon the relay R^{11} through its armature 2^{r11} , the conductor 87 and the contacts 90. The energization of the relay R^{11} also brings the armature 3^{r11} which is grounded in connection with the conductor 88 when circuit can be traced through the lamp SL to battery B^3 . The lamp SL will therefore be lighted and indicate that the impulse sending apparatus of the equipment has been set to effect a call. Another effect of the energization of the relay r^{11} is the breaking of the ground connection of the wire 78 through the armature 3^{r11} . The ground connection of the wire 78 is however, maintained through the wire 87 and connections just traced.

The final act of the operator in manipulating her apparatus to connect up and call a wanted subscriber, which final act consists in pressing the starting key SK, may occur when the drum of the impulse sending machine (see Figs. 5 and 6) is at any stage of a revolution. As has been before pointed out however, it is desirable that the sending of impulses shall begin at a predetermined point on the circumference of the drum, contacts and connections having been pointed out by which this result is accomplished. Diagrammatically these contacts are represented in Fig. 19 as normally closed contacts 89 and 90 which are adapted to be successively opened by the passage of a projection e upon the disc d which corresponds to that section of the drum of the sending machine over which the particular contacts are located. As shown in Figs. 5 and 6, it is more desirable from a mechanical standpoint that the buttons actuating the contacts 89 and 90 should fall into depressions of the drum in order to cause an opening of the contacts. For purposes of illustration in the diagram of Fig. 19 however, these contacts are shown as adapted to be opened by a projection on the drum. It will readily be understood that so far as effecting connections is concerned there is no difference in the two modes of operating the contacts and that one or the other means would be used

according as convenience of construction might indicate.

It being assumed then that the operator has set up the buttons of her key set, as described, and that the starting key SK has been depressed, as described, the sending of the switch actuating impulses will not be immediately begun. The initiation of the sending of these impulses will occur upon the passing of the projection *e* beneath the actuating buttons of the contacts 89 and 90, thereby opening them, and as has been noted, the drum of the sending machine is so arranged with relation to the contacts which it actuates that this successive opening of the contacts will take place just prior to the passage of the thousands elevations beneath the impulse sending contacts. As the disk *d* revolves the projection *e* will first come in contact with the button 91 of the contacts 90 and these contacts will be opened. This breaks one ground connection of the relay R^{11} , but the relay R^{12} being energized the ground connection of the relay R^{11} will be made through the armature $3^{R^{12}}$. The contacts 90 will then be permitted to close when the ground connection through them will be again restored to the relay R^{11} . The relay R^{11} has, therefore, not been deprived of current by the operation of contacts 90. The projection *e* will now open the contacts 89 thereby breaking the sole ground connection of the relay R^{12} which will thereupon become deenergized and its armatures will be released. It will now be seen that the relay R^{11} being energized and the relay R^{12} being deenergized, the impulse sending conductors 82 and 83 are connected with the conductors 76 and 77 so that the sending of impulses will commence. The condition of energization of the relays R^{11} and R^{12} will continue during a predetermined movement of the drum of the sending machine, in this case the entire revolution, when the projection *e* will open contacts 90 and remove the sole ground connection of the relay R^{11} , and the armatures of that relay falling back, the connections between the wires 82 and 83 on the one hand and the conductors 76 and 77 on the other will be broken. The conductors 82 and 83 being connected with the conductors 76 and 77, as described, an inspection of the machine shown in Figs. 5 and 6 will show that immediately after the establishment of the connection of these conductors the contact operating buttons will enter upon the elevation corresponding to the thousands row OK of the operator's key set. This will result in the closing of the contacts 107, the energization of the relay R^{13} and the connection of the common wire 170 of the thousands row of the key set with the conductor 83. It having been assumed that the fourth key of the row OK has been depressed, only the impulses produced

through the contacts of the sending machine corresponding to that button will be impressed upon the conductor 83. In this case then circuit may be traced from the battery wire 105 through the contacts 104, 70 the common wire 171 of the vertical impulse sending contacts through the contacts 100, conductor 172, conductor 173, contacts of the fourth push button of the row OK, common wire 170 and contacts 94' and 95' 75 of the relay R^{13} to the wire 83. This particular pair of contacts 100 which corresponds to the fourth button of the row is adapted to remain closed during four closures of the contacts 104 and therefore four 80 impulses will be transmitted to the conductor 83 during the passage beneath the contact actuating buttons of that portion of the drum of the sending machine which is assigned to the production of thousands impulses. Similarly any other number of thousands impulses might be impressed upon the conductor 83 by selecting any other one of the buttons of the row OK when their corresponding contacts in the group including the pairs 94 to 103 inclusive would transmit the proper number of vertical impulses to the conductor 83. Between the passage of the thousands portion of the drum of the sending machine and the commencement of the passage of the hundreds portion of that drum beneath the contact operating buttons of the vertical sending contacts, the contacts 93 will be closed once thereby throwing ground upon the conductor 82 which will serve to send a rotary impulse to the automatic switches. 95

After the rotary impulse has been sent the contacts 108 will be closed whereupon the relay R^{14} corresponding to the hundreds row of the key set will be energized and the common wire of that set will be connected with the conductor 83 and vertical impulses will be applied to that conductor according to which one of the keys of the set is depressed. In the present instance this key is assumed to be the sixth one from the left and connections may be traced from the battery wire 105 through the contacts 104, 105 wire 171, contacts 98, conductor 174, conductor 175, contacts of the sixth button of the row OK', conductor 176, and contacts of the relay R^{14} to the conductor 83. After the sending of the hundreds vertical impulses, a rotary impulse will be again sent over the conductor 82, as before described. After the sending of this rotary impulse the contact 109 will be closed thereby energizing the relay R^{15} and connecting the common wire of tens row OK² through the contacts of the relay last referred to with the conductor 83 and, it being assumed in this instance that the second button of the tens row is depressed, circuit may be traced through the contacts 104, 102, and 110 120 125 130

the second button of the tens row to the common wire of the row and thence to the conductor 83. A rotary impulse will then be sent and this will be succeeded by the 5 closing of the contacts 110 whereupon the relay R^{16} will be energized and the common wire of the units row OK^3 will be connected through the contacts of the relay last mentioned with the conductor 83. 10 It being supposed in the case of the units that the eighth button is depressed, the contacts 96 will be connected with the common wire of the set and eight impulses will be transmitted to the conductor 83. A rotary impulse will then be sent over the wire 15 82. The impulses thus far described as having been sent are sufficient to select the line of the subscriber wanted. As has before been stated, however, it may be desirable to select any one of several subscribers upon a party line. To select the proper means for calling this particular subscriber of the party line without disturbing the remainder of the parties upon that 20 line, reference has already been made to selective apparatus and it has been stated that this selective ringing apparatus is controlled by the keys of the row OK^4 . In the present instance the party wanted is supposed to be designated by the number 1. The operator has therefore depressed the first button of the row OK^4 . After the sending of the last rotary impulse, therefore, resulting in the connection of the desired line, the 25 contacts 111 are closed, whereupon circuit to the wire 83 will be completed from battery wire 105 through the contacts 104, contacts 103, the contacts of the first button of the row OK^4 , the common wire of that row, 30 and contacts of the relay R^{17} to the conductor 83.

Through circuits which have before been traced through the apparatus shown in Figs. 16, 17 and 18, the conductor 82 is connected 45 with the wire 64 (see Fig. 12) and thence through relay R^5 to battery, while the conductor 82 is connected to the conductor 63 and thence through the relay R^4 to ground. Upon the energization of the relay R^5 the 50 talking trunk conductor 62 will be broken apart from the wire 60 and the wire 62 will be connected through the armature r^5 , conductor 177, the armature 2^4 , and the conductor 178 to battery. At each impulse of 55 current therefore, through this relay R^5 , the rotary or sleeve conductor 62 of the trunk will be connected to battery. Upon each energization of the relay R^4 the tip or the vertical conductor 61 of the talking trunk 60 will be broken apart from trunk conductor 59 and will be connected to battery through the armature r^4 , conductor 179 and armature 2^5 . The impulses of current are thrown upon the relays R^4 and R^5 in an 65 order and manner as has been described

and control the order and number of impulses sent over the conductors 61 and 62.

Referring now to Figs. 13 and 14 connection may be traced from the trunk conductor 61 through the side switch arm s^{10} 70 and the relay V to ground. Battery connections being thrown on the conductor 61 in a manner as before described, the relay V will be energized as many times as the battery is applied to the conductor 61 and at each impulse of current will close the circuit from the ground through its own contacts 180 and 181, contacts 182 and 183 of the relay T and thence through the vertical magnet v and conductor 184 to the battery wire 185. This vertical magnet v being energized a number of times, in this case four, will step up the spindle of the switch S' by four steps when the wipers 75 s^{16} will be opposite the row of bank contacts containing the contacts s^{18} and the row of bank contacts corresponding to the thousands group containing the subscriber's line wanted which in this case is in the four thousands. Following the series of impulses 80 sent over the vertical wire 61, an impulse, as described, will be sent over the rotary wire 62, the circuit being traceable through the side switch arm s^{12} , conductor 186 and the magnet V^3 to ground. The energization of 85 the magnet V^3 closes the contacts 180 and 187 when circuit is traceable from the ground through the contacts 180 and 187 and the relay T to the battery wire 185. The energization of the relay T results through a 90 well known mechanism of the Strowger switch to step the side switch arms one step, when the side switch s^8 will rest upon its second contact and circuit is traceable from the ground through the switch arms s^8 , conductor 188, the rotary magnet v' and the conductor 184 to the battery wire 185. The relay v' is of the vibrator type, making and breaking its own circuit, and the attraction and release of its armature will continue until the circuit of this relay is broken. 95 The vibration of the armature operates through well known mechanism to turn the spindle of the switch S' upon its axis and this is continued so long as the test wiper 100 s^{20} finds ground upon its co-operating bank contacts as s^{22} , the contacts connected to busy apparatus being grounded while those of idle apparatus are open. As soon as the wiper s^{20} engages a non-grounded contact the 105 test circuit is opened and the switch comes to rest with its wipers resting upon contacts of a non-busy trunk.

The next set of vertical impulses over the 110 wire 61 and the following rotary impulse 115 over the wire 62 will now be respectively transmitted to the conductors 112 and 113 (it being understood that these impulses correspond to the hundreds digit of the subscriber's number) and will operate the hun- 120 125 130

dreds switch S^2 in a similar manner to that described in connection with the operation of the thousands switch S' to select an idle trunk in the group of hundreds in which the 5 wanted subscriber's hundreds digit is located. Thus in the present instance the spindle of the switch S^2 will be stepped up six times by the operation of the vertical magnet v^2 under the control of the vertical relay V' , 10 when the wipers s^{23} will be opposite contacts of the row of trunks in the sixth hundreds group, this row containing the stationary contacts s^{24} . The vertical stepping of the switch S^2 having been completed, a 15 rotary impulse will be sent over the wire 113 whereby the side switches will be stepped forward once and the rotary magnet v^3 will turn the switch spindle upon its axis until an idle pair of bank contacts as 20 s^{24} is reached, when the side switches will be moved into their final position and the rotation of the switch spindle will be arrested. The wipers s^{23} are now in contact with bank contacts s^{24} and therefore the trunk 25 conductor 112 is connected with the conductor 114 while the conductor 113 is connected with the conductor 115. All of the selector switches of the equipment shown in the drawings have now been operated, 30 but as has been referred to hereinbefore, these selectors might be multiplied in a well known manner according to the number of subscribers to be served. The only remaining switch to be operated is the connector 35 S^3 . A connector switch differs from a selector switch in this: That whereas the selector switches are each stepped by a definite number of impulses so that its contacts are brought opposite a row corresponding to 40 the desired group of trunks, one of which is to be connected, and then the contacts are automatically stepped along this row until the contacts of an idle trunk are reached, a connector switch is not only 45 stepped up by a definite number of impulses to a point opposite the row of contacts containing the terminals of the desired line, but it is also rotated step by step by a pre-determined number of impulses to bring the 50 wipers of the switch into engagement with the particular contacts in the row to which the desired line is connected. The next series of impulses sent after the operation of the switch S^2 is a series of vertical impulses, 55 in this case two, which is the hundreds digit of the wanted subscriber. These impulses coming over the line 114 traverse the relay V^2 thereby repeating the impulses through the vertical magnet v^4 which steps up the 60 spindle of the connector switch S^3 to the row of contacts containing the terminals of the wanted subscriber's line. A rotary impulse is now sent over the wire 115 and traversing the relay V^4 closes the circuit of 65 the relay T^2 whereupon the side switch arms

are moved into their second position. This transfers the connection made through the side switch arm s^{28} from the vertical magnet v^4 to the rotary magnet v^5 and the next series of vertical impulses, in this case 8, 70 over the wire 114 is repeated in the rotary magnet v^5 , and the spindle is rotated until the wipers s^{27} rest upon the contacts of the desired line. A rotary impulse is now sent over the wire 115, and operating the relay 75 T^2 moves the side switch arms into their third and last position, when the wires 116 and 117 of the trunk, which are connected through the condensers K^2 and K^3 with the conductors 114 and 115, are connected 80 through the contacts of the ringing relay R^{20} with the wipers s^{27} , and the wipers s^{27} are now in engagement with the contacts connected to the desired line. For purposes of illustration let it be assumed that the 85 subscriber's equipment, designated in Fig. 7 as B, together with its line relay N^b , its cut-off relay M^b and its multiple bank contact s^{28} correspond to the subscriber's station wanted, a pair of the contacts s^{28} being that 90 pair in the connector switch s^3 with which the wipers s^{27} engage. It is to be observed, however, that before the side switches of the connector S^3 take their final step that the wipers s^{27} have come into contact with 95 the contacts s^{28} , and if their connected substation is busy, the tip wiper s^{27} will become supplied by battery through the relay R^{18} or the relay R' of the trunk to which it is connected according to whether the 100 substation B was connected in as the result of a call of another subscriber or did itself 105 initiate the call. In either case the circuit can be traced from the battery through the wiper s^{27} , side switch arm s^{31} (now in its 110 second position), and conductor 195 to the contact 196 of the relay T^2 . When, therefore, the succeeding rotary impulse is received and the relay T^2 energized, the contact 196 will be thrown into engagement with 115 the contact 197 thereby connecting the wire 195 with one terminal of the release relay Q^2 the other terminal of that relay being connected to ground. The resulting operation of the armature of the release relay Q^2 120 throws a ground connection upon the release magnet q^2 which releases the holding dogs of the wipers of this connector switch in a manner well known in connection with Strowger switches and the switch S^3 is returned to its zero position.

It being assumed that the subscriber's line sought is not busy, and that the side switch arms of the connector switch have been 125 stepped into their final position, circuit can be traced from the ground through the cut-off relay M^b (see Fig. 8) through the sleeve contact s^{28} , the sleeve wiper s^{27} , side switch s^{30} and conductor 198 and relay R^{18} to battery. Circuit may now be traced from bat- 130

tery through armature r^{18} , conductor 199, armature 2^{19} and conductor 200 to the conductor 123 leading to the ringing apparatus. From the conductor 123 circuit may be traced through the relay R^{20} and the interrupter or commutator I^2 to ground. The relay R^{20} is thus energized and de-energized as the interrupter rotates and the contacts 201 and 202 are during its de-energization 10 permitted to engage with the contacts 203 and 204 respectively, thereby establishing the connection of the trunk wires 116 and 117 with the wipers s^{27} . During the energization of the relay R^{20} , the contacts 201 and 15 202 will be respectively thrown into engagement with the contacts 120 and 121 respectively, thereby establishing connection for the ringing circuit with the wipers s^{27} and at the same time disconnecting the trunk 20 conductors 116 and 117 therefrom. It will be apparent from the foregoing that when the relay R^{18} is energized that the cut-off relay M^b which is in series with it will also be energized when the armatures of the cut- 25 off relay referred to will establish the connections of the bank contacts s^{28} with the two sides of the line of the sub-station B. It will now be apparent that when the ringing apparatus is thrown upon the wipers s^{27} 30 and their engaging contacts s^{28} the ringer of the sub-station will be set in operation. As before noted, it has been supposed in the present instance that one of a number of sub-stations on a party line is desired and 35 it has been further supposed that this sub-station is designated by the number 1, and that the button in the operator's key set corresponding to that number has been depressed, also that the selector and connector 40 switches have operated to pick out the line to which the desired sub-station is connected. Succeeding transmission of the rotary impulse which operates to throw the side switch arms of the connector switch into 45 their last position and thereby to connect the subscriber's line with the trunk, there will be transmitted over the vertical side of the trunk and through the relay V^2 , one impulse which will be repeated over a circuit 50 which may be traced from the ground through contacts of the relay V^2 , contacts of the relay T^2 , conductor 205, the side switch arm s^{28} (which now is in its final position), the conductor 122 and the relay 55 R^{22} to the wire 123 which, as before indicated, is connected with battery. The relay R^{22} being energized, circuit may be traced from the battery wire 123 through the armature r^{22} , conductor 206, armature r^{24} , conductor 207 and relay R^{23} to ground. The energization of the relay R^{23} will result in 60 the locking of its battery connection through its armature 1^{23} , while the attraction of its armature r^{23} will establish a connection with the armature r^{25} of the relay R^{25} , the back 65 contact of which is connected with one terminal of the relay R^{24} . Upon the de-energization of the relay R^{22} which occurs after the passage of the impulse, and the release of the armature r^{22} , circuit can be traced 70 from the battery wire 123 through the armature r^{22} , the armature r^{23} , conductor 208, the armature of relay R^{25} , conductor 209 and the relay R^{24} to ground. The energization of the relay R^{24} results in the locking of 75 its battery connection through its armature 1^{24} , the establishment of a battery connection controlled by the relay R^{22} for the relay R^{25} and the breaking of the connection of the generator U' at the armature 2^{24} and 80 the engagement of that armature with its front contact which is connected with the generator U . Circuit may now be traced from the battery wire 250 through the generator U , armature 2^{24} , conductor 209, armature 2^{28} , conductor 210, armature 2^{28} , conductor 124, to the contact 120 of the ringing relay R^{20} , the contact 121 of that 85 relay being connected with the battery wire 250 as shown. When the ringing relay is 90 energized the contacts 120 and 121 will be respectively thrown into engagement with the contacts 201 and 202 which are connected with the wipers s^{27} of the switch whence 95 circuit may be traced as before through the subscriber's ringer and thus the generator U and the subscriber's ringers are connected in series in a closed circuit. Through 100 the circuit thus completed current passes through the ringers of all the subscribers upon the party line but only that ringer will be actuated which is attuned to the frequency of the particular generator connected in circuit. If, instead of sending a 105 single impulse as described for selecting the subscriber upon the party line, no party selecting impulse had been sent, the generator U' which is normally connected with the wire 124 would have remained so connected and a certain other subscriber on the party line would have been called. If the 110 party selecting impulses sent were greater than one the generator U^2 or U^3 would have been connected to the wire 124 according to the impulses sent, and, extending 115 this idea, any number of generators could be provided, any number of subscribers might be connected to a party line and any one of these subscribers could be selectively rung by the operator by sending the appropriate number of selective impulses. 120

The subscriber, as for instance at the sub-station B, having been rung up he removes his receiver from his hook and circuit will be established through his telephone from one side of his line to the other. This has the effect of placing a connection across the wipers s^{27} , and, at those intervals when the circuit of the ringing relay is broken at the 125 interrupter I and consequently the relay is 130

deenergized, the contacts 201 and 202 will respectively come into engagement with the contacts 203 and 204. At such times the trunk conductors 116 and 117 are connected together through the wipers s^{27} and the subscriber's telephone. This being the case, the relay R^{19} becomes energized, circuit being traceable from the ground through the relay R^{19} , trunk conductor 116, the contacts of the 10 ringing relay, the connector switch wipers and the subscriber's telephone, the side switch arm s^{30} , conductor 198 and relay R^{18} to battery. The relay R^{19} being energized, its armature 2^{19} will break the battery connection of the wire 123 and of the ringing relay R^{20} . This will result in the deenergization of the ringing relay whereupon the conductors 116 and 117 will remain continuously connected to the wipers s^{27} and the 15 subscriber's line until the apparatus is cleared out. The breaking of the battery connection to the wire 123, removes the connection on which are locked the relays (see Fig. 15) which establish the connections of 20 the selective ringing generator whereupon those relays will be restored to their normal position. The energization of the relay R^{19} will also result in the throwing of a battery connection upon one terminal of the relay 25 R^{21} , the other terminal of that relay being grounded. Circuit may be traced through this relay as follows: from the ground through the relay R^{21} , conductor 211, armature 1^{21} , conductor 212, conductor 213 and contacts 214 to the free terminal of battery. The relay R^{21} having been energized over the 30 circuit just traced, battery will be locked upon the relay through its armature r^{21} . Connection will be also established by the armature 1^{21} from one terminal of the release relay Q^2 of the connector switch to the back contact of the armature 1^{19} but, as will be seen, this armature is now attracted and therefore the circuit of the release relay is 35 open at this point.

The operations and connections for placing the two subscribers in communication are now complete and the connections remain as described until the conversation is 40 finished and the apparatus is cleared out. The clearing out is produced as a result of a hanging up of the receivers at the connected subscribers' stations.

Conversation having been completed, the 45 called subscriber hangs up his receiver thereby breaking the circuit through his telephone and breaking the connection between the two wipers s^{27} of the connector switch. This breaks the circuit through the relays R^{19} and R^{18} as before traced, whereupon the relay R^{19} is deenergized but the circuit of the relay R^{18} is still maintained through the subscriber's cut-off relay. Battery connection is now thrown upon the release relay Q^2 , through the contacts 214,

conductor 213, conductor 212, armature 1^{19} , armature 1^{21} and conductor 215. The other terminal of the release relay being grounded, this relay will be energized, when circuit will be established from the ground through the armature of the relay just referred to and the release magnet q^2 to the free terminal of battery. The release magnet of the connector switch being thus energized the switch will be restored to its normal position. Upon the restoration of the connector switch, the relay R^{18} will be deenergized. As the connector switch moves into its normal position, the contacts 214 will be opened by the switch spindle thereby breaking the battery connection of the relay R^{21} which thereupon becomes deenergized. It will now be seen that the hanging up of his receiver by the called subscriber will result in the clearing out of his connector switch and that the relays of the talking trunk concerned directly in the operation of the switch will be cleared out.

When the calling subscriber hangs up his telephone receiver, circuit will be broken through the relays R and R' (see Fig. 12), as hereinbefore traced, whereupon the relay R will become deenergized but the relay R' will remain energized through the calling subscriber's cut-off relay. The deenergization of the tip-relay R results in the breaking of the battery connection of the wire 48 through the armature r whereupon the tens and units relay of the primary selector concerned in the connection of the calling subscriber with the trunk, will be deenergized and the selector will be in readiness to perform another connecting operation while the calling subscriber's line will be disconnected from the talking trunk. This will result in the breaking of the circuit through the relay R' and the subscriber's cut-off relay whereupon the cut-off relay will be deenergized and its cooperating apparatus placed in condition to effect another connection upon the initiation of a call by its subscriber, and also the relay R' will be deenergized. The release of the armature 3^r establishes the connection of the wire 70 with ground, thereby removing the busy test from the trunk distributing relay as before referred to. The release of the armature r' removes the battery connection which is locked on the relays R^3 and R^2 by the armature 2^r whereupon those relays will become deenergized. All of the relays R to R^3 inclusive, thus become deenergized and the apparatus is in condition for connecting another subscriber with a talking trunk. It will be noted that the relay R is deenergized an interval of time before the relay R^2 is deenergized. Between the deenergization of the relay R and that of the relay R^2 , battery will be thrown on both the tip and sleeve conductors 59 and 60 of the talking trunk.

through the armature r^2 and the armatures 1^r and 2^r , as has been before referred to. This throws battery upon the trunk conductors 59 and 60 which are connected with the conductors 61 and 62 which are connected through the first selector switch S' with the conductors 112 and 113, the last mentioned conductors being connected through the second selector switch S^2 with the trunk conductors 114 and 115. The battery connections thus thrown upon the trunk conductors 114 and 115 will result in the simultaneous energization of the relays V^2 and V^4 when circuit may be traced from the armature r^{19} of the relay R^{19} through the conductor 216, contacts of the relays V^2 and V^4 , conductor 217, test contact s^{26} , wiper s^{25} of the second selector switch S^2 , conductor 218, release relay Q' , and side switch arm s^{15} to ground. The release relay being thus energized, the release magnet q' of the selector switch S^2 will be energized and the selector switch will be released. The battery connection to the armature r^{19} is effected either through the wire 219 or the wire 220 and the release magnet q^2 , according to whether or not the relay R^{19} is energized.

The selector switch S^2 having been restored as described and its switch arms being in their first positions as shown in Fig. 13, the battery connections upon the trunk wires 112 and 113 are extended to the relays V' and V^3 . These relays are thereupon simultaneously energized when circuit may be traced from the free terminal of battery through the release magnet q' , the contacts of the relays V' and V^3 , the test contact s^{22} of the first selector switch S' , the test wiper s^{20} , the release relay Q and the side side-switch arm s^{14} to ground. The release relay Q having thus been energized the circuit of the release magnet q will be closed and the first selector switch will be returned to its normal position. All the selector and connector switches of the talking trunk and the various relays of the talking trunk have now been restored and are idle in readiness for establishing another connection between two subscribers.

In regard to the clearing out of the operator's equipment, it has been already pointed out how an operator's equipment becomes connected with the talking trunk and the sending of the impulses for operating the automatic switches is initiated. The drum of the machine continuing to revolve, the impulses corresponding to the number set up on the operator's key-set will be transmitted to the automatic switches and then the projection e will open the contacts 90. This removes the ground connection locked on the relay R^{11} through its armature 2^{11} . Upon the deenergization of the relay R^{11} its armatures r^{11} and 1^{11} will fall back,

breaking the connections of the impulse wires 83 and 82 with the trunk. The operator is notified of the completion of the operation of the sending machine by the extinguishing of the lamp SL , the circuit of which is broken when the armature 3^{11} of the relay R^{11} falls back. The operator may now withdraw her plug P from the jack J and utilize her equipment in connection with any other secondary selector by inserting the plug into the jack corresponding to that selector.

Upon the removal of the plug P the circuit of the relay R^8 is broken at the contact j^a of the jack J . Its armatures thereupon fall back and break the battery connection of the relay R^7 and also the ground connection of the tens and units relays of the secondary selector, the circuit of these tens and units being hitherto made through the wire 74. The apparatus by which the operator's equipment was operatively associated with the talking trunk is now cleared out and may be made use of for establishing the connections of other trunks.

It is to be observed that with the apparatus shown any one of a plurality of trunks may be operatively associated with any one of a plurality of operators' equipments so that an idle operator's equipment is available for use in connection with any one of a plurality of talking trunks. As each operator's equipment requires but a short time in which to perform its functions and as the trunks do not all require service by an operator simultaneously, the number of operators' equipments and their connecting lines may be very much less in number than the number of talking trunks served. The flexibility of the system is further increased by the plug and jack connection described whereby any operator's equipment may be connected with any secondary selector. This also provides means whereby operator's equipments auxiliary, or in addition to those ordinarily required may be brought into use during the busiest portions of the day, additional operators if necessary, being assigned to manipulate these additional sets. All the operator's equipments being exactly alike, the auxiliary sets will be plugged into the secondary selectors in the manner as has been described.

In Figs. 20 and 21 is shown a modified means for effecting connection between a secondary selector and an operator's equipment. The apparatus of Fig. 21 is exactly like that shown in Fig. 19 (except that in the modified apparatus the signal lamp for advising the operator of a call is located in the apparatus shown in Fig. 21 as will hereinafter appear) and performs the same functions. The apparatus shown in Fig. 20 illustrates intermediate connections between

the apparatus shown in Fig. 21 and a secondary selector as shown in Fig. 16. The relation of these modified operator's connections to the apparatus as a whole will be immediately perceived on substituting Figs. 20 and 21 for the Figs. 17, 18 and 19 in the system hereinbefore described as a whole. According to the modified connections of Figs. 20 and 21 the operator's equipment is connected permanently with the secondary selector to which it is assigned. Referring now to Fig. 20 it will be seen that the wires 75', 74' and 71' and 72' are respectively extensions of the wires 75, 74, 71 and 72 of the apparatus shown in Fig. 16.

It being assumed that the secondary distributing switch SDS has selected a secondary distributing relay as SDR, the circuit of that relay will be completed through the wire 75' and the armature 1^{r28} of the armature of the relay R^{28} , to ground. It will also be supposed that the connections of the wires 71' and 72' have been completed through the secondary selector to the talking trunk, the tens and units relays for effecting this connection having been initially energized in a manner as before described and having their battery connection locked, ground connection being made through the wire 74', wire 74' being connected with ground through the armature 4^{r30} or the contacts 90'' (see Fig. 21).

The conductors 71' and 72' being connected through with the talking trunk as described, circuit may be traced from the ground through the relay R^{29} , the conductor 220, armature 2^{r30} of the relay R^{30} , conductor 72' and thence through the secondary selector, the wire 64, and the relay R^5 to battery. The armatures of the relay R^{29} being attracted, the armature r^{29} throws battery upon one terminal of the relay R^{28} , the other terminal of that relay being initially controlled by the relay R^{30} and cleared out by the openings of the contacts 90 at the end of the sounding of a set of impulses by which a wanted subscriber is connected. The energization of the relay R^{29} also closes the circuit of the signal lamp L' by which the attention of the operator is attracted to the call. The circuit of this lamp may be traced from the ground through the armature 1^{r29} , conductor 221, armature r^{31} , conductor 222 and the lamp L' to battery.

The operator having noted the lighting of her signal lamp L' , she first depresses her listening-key LK' thereby throwing ground connection upon the relay R^{31} , the other terminal of that relay being connected with battery. The relay R^{31} being energized its armatures 1^{r31} and 2^{r31} will respectively connect the wires 223 and 224 with the wires 72' and 71' which lead through the secondary selector to the magnets of the relays R^6 .

and R^4 and also to contacts of the relay R^6 . The operator's telephone being connected across the wires 223 and 224, this telephone is connected across the talking trunk wires 59 and 60 and conversation may be carried on as before described.

The operator having ascertained from the calling subscriber the number of the wanted subscriber, she sets up this wanted number upon her key-set as before set forth. She then depresses her starting-key SK' whereupon ground is thrown upon the relay R^{32} and also upon the relay R^{28} . The relay R^{32} thereupon becomes energized. The relay R^{28} first finds ground through the contacts 90 or the armature 4^{r30} . Being energized upon its connection to battery as described, its armature r^{28} will lock its battery connection while its armature 1^{r28} will break the ground connection of the wire 75', thereby opening the circuit of the relay R^{28} and placing a busy test upon it.

The energization of the relay R^{32} breaks connection of the impulse wires at the armatures r^{32} and 1^{r32} , locks ground upon itself through the starting contacts 89'' by its armature 2^{r32} and throws ground upon the relay R^{30} through the armature 3^{r32} .

The relay R^{30} being energized, the battery connection of the relay R^{29} is broken at the armature 2^{r30} , the circuit of the operator's signal lamp is broken at the armature 1^{r29} and the battery connection of the relay R^{28} is broken at the armature r^{28} . Ground connection is locked upon the relay R^{29} through the contacts 90'' and the armature 3^{r30} . These contacts 89'' and 90'' correspond to the contacts 89 and 90 and 89' and 90' shown in Figs. 19, 5 and 6 and described in relation thereto. The armature 4^{r30} throws ground upon the lamp SL' , thereby lighting it, this lamp corresponding to the lamp SL in Fig. 19.

The sending of the impulses is initiated at a predetermined portion of the circumference of the drum of the sending machine by means of the contacts 89'' and 90'' acting in conjunction with the relays R^{32} and R^{30} in a manner as hereinbefore described in connection with the apparatus of Figs. 18 and 19.

The desired set of impulses having been transmitted the secondary selector of the operator's equipment will be cleared out upon the opening of the contacts 90'' when the relay R^{30} will be deenergized, the circuit of the tens and units relays of the secondary selector will be opened and the circuit of the relay R^{28} is broken. When the armatures of the last mentioned relay fall back, the armature 1^{r28} establishes the ground connection of the trunk distributing relay thereby removing its busy test. The secondary selector and relays of the operator's

equipment are now restored and in readiness for establishing the connections and sending the impulses to connect two other sub-stations between which communication is desired.

- Fig. 1 shows a schematic diagram of a system in which are separate exchanges or central offices E^x , E^{x1} , E^{x2} and E^{x3} . Between these exchanges extend talking trunks indicated by the group of fine lines TT to TT^3 inclusive, each exchange in the system shown being connected with every other exchange of the system by talking trunks. Connected by appropriate lines with each of the several exchanges of the system are a plurality of sub-stations SS to SS^3 inclusive. Located at each of the exchanges are the necessary primary selectors and connector switches as hereinbefore described for establishing connection between any two lines of a particular exchange or between the lines of different exchanges. The operator's equipments for controlling the operation of the connecting apparatus at all of the exchanges are grouped at one exchange E^x and from this exchange operator's trunks OT , OT^1 , and OT^2 over which the effecting of the connections of the talking trunks is controlled, extend to all of the other exchanges.
- The primary selectors and connector switches governing the connections of the subscribers' lines terminating in an exchange are located at that exchange but the distribution of the selector switches between the exchanges will depend upon the apportionment of subscribers between the exchanges. The arrangement of the selector switches is always such that the selector switches at an exchange to which a corresponding subscriber is connected, when an operator transmits switch-operating impulses corresponding to the wanted subscriber, the selector switch or switches will connect the corresponding subscriber's line with that of a wanted subscriber if both of these subscribers' lines terminate in the same exchange, or will select a talking trunk leading to the exchange to which the wanted subscriber's line is connected and will there operate the necessary automatic switches to connect the wanted subscriber's line. As an example, let it be supposed that there are one thousand subscribers' lines connected with each of the exchanges shown, those subscribers having numbers in the two-thousands being connected to the exchange E^x , those in the three-thousands to exchange E^{x1} , those in the four-thousands to exchange E^{x2} and those in the five-thousands to exchange E^{x3} . Upon the call of a subscriber at any of the sub-stations as E^{x2} and an indication of his desire to be connected with a subscriber at another of the exchanges as for instance the exchange E^{x3} , when the sub-

scriber will have a number in the five-thousands, the operator will send impulses according to the number of the wanted subscriber, when the first selector switch will pick out the fifth-thousands group. This group of conductors runs to the exchange E^{x3} and after having selected this group the first selector at the exchange E^{x2} will select an idle trunk of this group. This having been done, impulses will be sent over the connected trunk to the second selector and connector switches at the exchange E^{x3} and the connection effected or a busy test developed as has been before described in detail. In a similar manner a hundreds group of conductors leading between exchanges might be selected whereby one-hundred subscribers or less may be connected with an exchange and other distributions of subscribers between the exchanges and the manner of selecting the exchanges and connecting the individual subscribers will be readily made after the foregoing description by any one skilled in the art, according as circumstances may dictate.

In Fig. 2 is also shown a schematic diagram of a system which shows an arrangement of apparatus slightly more in detail. Moreover the system of Fig. 2 differs from that of Fig. 1 in that the operators' equipments are grouped at a point separate from all the exchanges into which the subscribers' lines of the system converge instead of being located at one of those exchanges.

The exchanges designated by E^{x4} , E^{x5} and E^{x6} respectively, have each connected to them a group of subscribers' lines conventionally illustrated in the same manner as in Fig. 1 and, as in Fig. 1, the talking trunks extending between exchanges are represented by fine lines while the conductors over which the operators control the connections and which extend from the point CH at which the operators' equipments are located to each of the exchanges, are represented by coarse lines. Each of the exchanges E^{x4} to E^{x6} inclusive are conventionally illustrated in Fig. 2 in the same manner and therefore a description of one of them will be a description of each thus, at the exchange E^{x5} are located primary selectors indicated by PS and selector and connector switches designated as a whole by SC . The subscribers' lines are multiplied between the primary selector and the connector switches as shown while talking trunks designated by TT^6 extend from the primary selector to the first selector switch. Operatively associated with the trunks TT^6 are operators' trunks OT^3 which extend to the clearing house at which the operators' equipments are located.

In Fig. 3 is shown a diagram similar to Fig. 2, each of the exchanges E^{x4} , E^{x5} and

E^{x_6} being shown as having connected subscribers' stations, primary selectors and selector and connector switches as indicated in Fig. 2.

- 5 According to the system shown in this diagram however, the secondary selectors, indicated by S^{x_1} to S^{x_6} inclusive are located at the exchanges. This is an important feature of the present invention for as has been 10 before pointed out the number of operators' equipments and the operators' trunks indicated by the coarse lines O^{x_4} , O^{x_5} and O^{x_6} whereby they are connected with the secondary selectors may be very much less in number 15 than the talking trunks which are served so that the number of trunks and their conductors which extend from the exchanges to the clearing house may be of a greatly reduced number.
- 20 In Fig. 4 is shown the exchanges E^{x_4} , E^{x_5} , and E^{x_6} , each of the exchanges having subscribers' lines connected thereto, selector and connector switches SC, primary selectors PS, talking trunks TT^x extending between the primary selectors and the selector switches, and a secondary selector as S^{x_6} connected by an operator's trunk as OT^x with the operator's equipment at the clearing house CH. The system of Fig. 4 differs however, from that shown in Fig. 3 in 25 that talking trunks, which are represented by the fine lines, do not extend directly between each exchange and every other exchange but between certain only of the exchanges thus, in the diagram of Fig. 4 the exchange E^{x_4} has talking trunks extending to the exchange E^{x_5} and there are also talking trunks extending between the exchanges E^{x_5} and E^{x_6} but no talking trunks extending 30 between the exchanges E^{x_4} and E^{x_6} . Connections between subscribers' lines located respectively at the last mentioned exchanges are effected through the exchange E^{x_5} , suitable selector switches and connections being provided at the exchange last 35 mentioned whereby talking trunks extending from the exchange E^{x_6} to the exchange E^{x_5} may be connected to the trunks extending between the exchanges E^{x_4} and E^{x_5} , which switches and connections are controlled by the operator.

40 In some instances a subscriber, after calling may neglect to respond to the inquiry of the operator as to the number of the wanted subscriber for an undue length of time, or for other reasons the operator may wish to restore her apparatus so that the secondary selector and equipment may be made use of in connection with other calls, 45 without waiting for the impulse sending apparatus to come to its starting position. For this purpose normally closed contacts 50 (see Fig. 18) are provided and in the present instance are shown as of such a 55 character as to be adapted to be moved by

a push button in the usual manner. Upon the opening of these contacts 251 the ground connection of the wire 78 will be opened thereby deenergizing the relay R^9 whereupon the relay R^7 will also be deenergized 70 and the apparatus is again in position to serve another calling trunk. The contacts 252 of Fig. 20 serve a similar purpose with relation to the modified connections shown 75 in this figure.

By means of the contacts 253 of Fig. 20, the ground connection of the wire 75' may be controlled at will by the operator. When these contacts are opened the ground connection will be removed from the wire 75' 80 which, as has before been seen, is connected with the secondary distributing relay SDR and thus the whole secondary selector and its connected operator's equipment are thrown out of service for as long a time as 85 the operator chooses to keep the contacts 253 open, the opening of the contacts 253 serving to place at the will of the operator what might be considered a busy test upon the secondary distributing relay SDR. 90

In Fig. 19 the lamps 1' to 1⁶ inclusive serve the purpose of resistances which prevent the currents, in the conductors in which the lamps are inserted, from becoming unduly large. A similar function is 95 performed by the corresponding lamps shown in Fig. 21.

100 While the foregoing description in connection with the drawings serves fully to illustrate the present invention, it will be readily understood that various modifications may be made in the apparatus shown as circumstance may require and as are made perfectly clear to those skilled in the art by the foregoing descriptions in connection with the drawings and therefore the invention is not limited to the apparatus shown. 105

What I claim is:

1. In a telephone exchange system, the 110 combination with a plurality of exchanges, of a plurality of subscribers' lines connected with each of said exchanges, each of said exchanges comprising automatic switches for effecting connections between subscribers' lines, talking trunks extending between said exchanges, operators' equipments comprising means for controlling said automatic switches and grouped at an office separate from said exchanges and operators' 115 trunks extending from said office to said exchanges. 120

2. In a telephone exchange system the combination with an exchange, of a plurality of subscribers' lines connected thereto, said exchange comprising a plurality of talking trunks, means for connecting a calling subscriber with an idle one of said talking trunks, and selector switches associated 125 with said trunks, operators' equipments com- 130

prising means for controlling said selector switches and located at an office separated from said exchange, and trunks less in number than said talking trunks extending from 5 said office to said exchange.

3. In a telephone exchange system, the combination with an exchange, of a plurality of subscribers' lines connected thereto, said exchange comprising talking trunks 10 for connecting subscribers' lines and automatic switches, operators' equipments comprising means for controlling said automatic switches and located at an office separate from said exchange, trunks extending from 15 said office to said exchange, and means located at said exchange for automatically selecting an idle operator's equipment.

4. In a telephone exchange system the combination with an exchange, of a plurality of subscribers' lines connected thereto, said exchange comprising automatic switches, talking trunks for connecting subscribers' lines, and means for automatically connecting a calling subscriber's line with 25 an idle one of said talking trunks, operators' equipments comprising means for controlling said automatic switches and located at an office separate from said exchange, trunks extending from said office to said exchange, 30 and means at said exchange for automatically selecting an idle one of said operators' equipments.

5. In a telephone exchange system the combination with an exchange, of a plurality of subscribers' lines connected thereto, said exchange comprising automatic switches, talking trunks for connecting subscribers' lines, and means for automatically connecting a calling subscriber's line with 35 an idle one of said talking trunks, operators' equipments comprising means for controlling said automatic switches and located at an office separate from said exchange, means at said exchange for automatically selecting 40 an idle one of said operators' equipments, and trunks extending from said office to said exchange of a less number than said talking trunks.

6. In a telephone exchange system, the combination with an exchange, of a plurality of subscribers' lines connected thereto, said exchange comprising talking trunks for connecting subscribers' lines and automatic switches, operators' equipments comprising means for controlling said automatic switches and located at an office separate from said exchange, trunks extending from 55 said office to said exchange, and means located at said exchange for automatically selecting an idle operator's equipment, said trunks extending from said office to said exchange being less in number than said talking trunks.

7. In a telephone exchange system the

combination with an exchange, of a plurality of subscribers' lines connected thereto, said exchange comprising automatic switches and talking trunks for connecting subscribers' lines, operators' equipments comprising means for controlling said automatic switches and located at an office separate from 65 said exchange, operator's trunks extending from said office to said exchange, and means located at said exchange and controlled through said talking trunks for automatically selecting an idle one of said operators' trunks.

8. In a telephone exchange system the combination with an exchange, of a plurality of subscribers' lines connected thereto, said exchange comprising automatic switches and talking trunks for connecting subscribers' lines, operators' equipment comprising means for controlling said automatic switches and located at an office separate from 80 said exchange, operator's trunks extending from said office to said exchange, and means located at said exchange and controlled through said talking trunks for automatically selecting an idle one of said operators' trunks, said operators' trunks being 85 less in number than said talking trunks.

9. In a telephone exchange system, the combination with an exchange, of a plurality of subscribers' lines connected thereto, said exchange comprising selector switches, a plurality of talking trunks and automatic means for connecting a calling subscriber with an idle one of said talking trunks, operators' equipments comprising 90 means for controlling said selector switches and located at an office separate from said exchange, operators' trunks extending from said office to said exchange, and means set 95 in operation by the connection of a calling subscriber with one of said talking trunks, for selecting an idle one of said operators' equipments.

10. In a telephone exchange system, the combination with an exchange, of a plurality of subscribers' lines connected thereto, said exchange comprising selector switches, a plurality of talking trunks and automatic means for connecting a calling subscriber with an idle one of said talking trunks, operators' equipments comprising means for controlling said selector switches and located at an office separate from 110 said exchange, operators' trunks extending from said office to said exchange, and means set in operation by the connection of a calling subscriber with one of said talking trunks, for selecting an idle one of said operators' equipments, said operators' trunks being less 115 in number than said talking trunks.

11. In a telephone exchange system, the combination with a plurality of exchanges, of a plurality of subscribers' lines connected

- to each of said exchanges, each of said exchanges comprising a plurality of talking trunks, means for connecting a calling subscriber with an idle talking trunk and selector switches, operators' equipments comprising means for controlling said selector switches and located at an office separate from said exchanges, operators' trunks extending from said office to each of said exchanges and means located at each of said exchanges for selecting an idle operator's trunk.
12. In a telephone exchange system, the combination with a plurality of exchanges, of a plurality of subscribers' lines connected to each of said exchanges, each of said exchanges comprising a plurality of talking trunks, means for automatically connecting a calling subscriber with an idle talking trunk and selector switches, operators' equipments comprising means for controlling said selector switches and located at an office separate from said exchanges, operators' trunks extending from said office to each of said exchanges and means located at each of said exchanges for selecting an idle operator's trunk.
13. In a telephone exchange system, the combination with a plurality of exchanges, of a plurality of subscribers' lines connected to each of said exchanges, each of said exchanges comprising a plurality of talking trunks, means for connecting a calling subscriber with an idle talking trunk and selector switches, operators' equipments comprising means for controlling said selector switches and located at an office separate from said exchanges, operators' trunks extending from said office to each of said exchanges and means located at each of said exchanges for selecting an idle operators' trunk, the number of said operators' trunks extending to an exchange being less than the number of talking trunks at that exchange.
14. In a telephone exchange system, the combination with subscribers' lines, of a plurality of groups of connecting apparatus, each comprising talking trunks and automatic switches, operators' equipments, each comprising means for controlling said automatic switches, trunks extending from said operators' equipments to each of said groups, the last mentioned trunks extending to a group being less in number than the talking trunks of the group, and an impulse sending device common to said equipments.
15. In a telephone exchange system, the combination with a plurality of exchanges, of a plurality of subscribers' lines connected with each of said exchanges, automatic selector and connector switches and talking trunks at each of said exchanges, talking trunks extending between said exchanges, a plurality of operators' equipments, each comprising means for operating said selector and connector switches and located at an office removed from said exchanges, and connector switches and located at an office removed from said exchanges, and comprising means for operating said selector 65 and connector switches and located at an office removed from said exchanges, and trunks extending from said office to each of said exchanges, the number of the last mentioned trunks extending to an exchange being less than the number of talking trunks at that exchange.
16. In a telephone exchange system, the combination with a plurality of exchanges, of a plurality of subscribers' lines connected with each of said exchanges, automatic selector and connector switches and talking trunks at each of said exchanges, talking trunks extending between said exchanges, a plurality of operators' equipments, each comprising means for operating said selector and connector switches and located at an office removed from said exchange, and trunks extending from said office to each of said exchanges, and an impulse sending machine common to said equipments.
17. In a telephone exchange system, the combination with a plurality of exchanges, of a plurality of subscribers' lines connected with each of said exchanges, automatic selector and connector switches and talking trunks at each of said exchanges, talking trunks extending between said exchanges, a plurality of operators' equipments, each comprising means for operating said selector and connector switches and located at an office removed from said exchanges, trunks extending from said office to each of said exchanges, the number of the last mentioned trunks extending to an exchange being less than the number of talking trunks at that exchange, and an impulse sending machine common to said equipments.
18. In a telephone exchange system, the combination with a plurality of exchanges, of a plurality of subscribers' lines connected with each of said exchanges, automatic selector and connector switches and talking trunks at each of said exchanges, talking trunks extending between said exchanges, a plurality of operators' equipments, each comprising means for operating said selector and connector switches and located at an office removed from said exchanges, trunks extending from said office to each of said exchanges, and means at each of said exchanges for selecting an idle trunk extending to said office.
19. In a telephone exchange system, the combination with a plurality of exchanges, of a plurality of subscribers' lines connected with each of said exchanges, automatic selector and connector switches and talking trunks at each of said exchanges, talking trunks extending between said exchanges, a plurality of operators' equipments, each comprising means for operating said selector and connector switches and located at an

office removed from said exchanges, trunks extending from said office to each of said exchanges, and automatic means at each of said exchanges for selecting an idle trunk 5 extending to said office.

20. In a telephone exchange system, the combination with a plurality of exchanges, of a plurality of subscribers' lines connected with each of said exchanges, automatic selector and connector switches and talking trunks at each of said exchanges, talking trunks extending between said exchanges, a plurality of operators' equipments, each comprising means for operating said selector 10 and connector switches and located at an office removed from said exchanges, trunks extending from said office to each of said exchanges, and means at each of said exchanges controlled by the connection of a 15 calling subscriber's line with a talking trunk, for selecting an idle trunk extending to said office.

21. In a telephone exchange system, the combination with a plurality of exchanges, 25 of a plurality of subscribers' lines and instruments connected with each of said exchanges, each of said exchanges comprising selector switches, talking trunks connected with said selector switches and means controlled by the subscribers' instruments for connecting a calling subscriber's line with an idle one of said talking trunks, operators' 30 equipments located at an office separated from said exchanges and each comprising means for operating said selector switches, operators' trunks extending from said office to each of said exchanges, and means at each 35 of said exchanges, controlled by the connection of a subscriber's line with a talking trunk, for selecting an idle operator's trunk. 40

22. In a telephone exchange system, the combination with a plurality of exchanges, of a plurality of subscribers' lines and instruments connected with each of said exchanges, each of said exchanges comprising selector switches, talking trunks connected with said selector switches and means controlled by the subscribers' instruments for connecting a calling subscriber's line with an 45 idle one of said talking trunks, operators' equipments located at an office separated from said exchanges and each comprising means for operating said selector switches, trunks extending from said office to each of 50 said exchanges and means at each of said exchanges, controlled by the connection of a subscriber's line with a talking trunk for selecting an idle trunk extending from said office, the number of trunks extending from 55 said office to an exchange being less than the number of talking trunks at that exchange. 60

23. In a telephone exchange system, the combination with a plurality of exchanges, of a plurality of subscribers' lines and in-

struments connected with each of said exchanges, each of said exchanges comprising selector switches, talking trunks connected with said selector switches and means controlled by the subscribers' instruments for connecting a calling subscriber's line with an idle one of said talking trunks, operators' equipments located at an office separated from said exchanges and each comprising means for operating said selector switches, trunks extending from said office to each of 65 said exchanges and means at each of said exchanges, controlled by the connection of a subscriber's line with a talking trunk for selecting an idle trunk extending from said office, and an impulse sending device common to said equipments. 70

24. In a telephone exchange system, the combination with a plurality of exchanges, of a plurality of subscribers' lines and instruments connected to each of said exchanges, each of said exchanges comprising selector and connector switches, talking trunks connected with said selector switches and talking trunks connected with said connector switches and means controlled by the 85 subscribers' instruments for connecting a calling subscriber with an idle talking trunk connected to a selector switch, operators' equipments located at an office separated from said exchanges and comprising means for 90 controlling said selector and connector switches, operators' trunks extending from said office to each of said exchanges, means at each of said exchanges controlled by the connection of a subscriber's line with a talking trunk connected with a selector switch, 95 for selecting an idle one of said operators' trunks, and talking trunks extending between said exchanges. 100

25. In a telephone exchange system, the combination with a plurality of exchanges, of a plurality of subscribers' lines and instruments connected to each of said exchanges, each of said exchanges comprising selector and connector switches, talking trunks connected with said selector switches and talking trunks connected with said connector switches and means controlled by the subscribers' instruments for connecting a calling subscriber with an idle talking trunk connected to a selector switch, operators' equipments located at an office separated from said exchanges and comprising means for 110 controlling said selector and connector switches, trunks extending from said office to each of said exchanges, means at each of said exchanges, controlled by the connection of a subscriber's line with a talking trunk connected with a selector switch, for selecting an idle one of said trunks extending from said office and talking trunks extending between said exchanges, the number of trunks extending from said office to an exchange being 115 120 125

less in number than the number of talking trunks connected with selector switches at that exchange.

26. In a telephone exchange system, the combination with a plurality of exchanges, of a plurality of subscribers' lines and instruments connected to each of said exchanges, each of said exchanges comprising selector and connector switches, talking trunks connected with said selector switches and talking trunks connected with said connector switches and means controlled by the subscribers' instruments for connecting a calling subscriber with an idle talking trunk connected to a selector switch, operators' equipments located at an office separated from said exchanges and comprising means for controlling said selector and connector switches, trunks extending from said office to each of said exchanges, means at each of said exchanges controlled by the connection of a subscriber's line with a talking trunk connected with a selector switch for selecting an idle one of said trunks extending from said office and talking trunks extending between said exchanges, the number of trunks extending from said office to an exchange being less in number than the number of talking trunks connected with selector switches at that exchange, and an impulse sending device common to said equipments.
27. In a telephone exchange system, a plurality of lines, automatic switches, adapted to interconnect the lines, operator's selective means adapted to be brought into connection with the switches, and a controlling or sending machine therefor comprising the following instrumentalities; a supporting frame fitted with suitable bearings, a drum having a shaft mounted to turn in said bearings, a motor connected to said drum, a plurality of contact springs overlying the drum, and cams on the surface of the drum adapted to work said springs to make and break their contacts.
28. A semi-automatic telephone system including telephone lines, a main exchange in which a portion of said lines terminate, a branch exchange in which a portion of said lines terminate, trunk lines interconnecting said exchanges, means for automatically connecting a calling line of said branch exchange over an idle one of said trunks with said main exchange, and impulse controlling mechanism at said main exchange for transmitting directive currents back over said same trunk to link the calling line to the called line.
29. A semi-automatic telephone system including telephone lines, a main exchange in which a portion of said lines terminate, a branch exchange in which a portion of said lines terminate, trunk lines interconnecting said exchanges, means for automatically connecting a calling line of said branch ex-

change over an idle one of said trunks with said main exchange, impulse controlling mechanism at said main exchange for transmitting directive currents back over said same trunk to link the calling line to the called line, and means for thereon freeing the trunk while leaving the connection of subscribers continuing.

30. A semi-automatic telephone system including telephone lines, a main exchange in which a portion of said lines terminate, a branch exchange in which a portion of said lines terminate, trunk lines interconnecting said exchanges, means for automatically connecting a calling line of said branch exchange over an idle one of said trunks with said main exchange, impulse controlling mechanism at said main exchange for transmitting directive currents back over said same trunk to link the calling line to the called line, and switches at the substations of lines so connected for rendering them idle when disconnection is desired.

31. A semi-automatic telephone system including telephone lines, a main exchange in which a portion of said lines terminate, a branch exchange in which a portion of said lines terminate, trunk lines interconnecting said exchanges, means for automatically connecting a calling line of said branch exchange over an idle one of said trunks with said main exchange, impulse controlling mechanism at said main exchange for transmitting directive currents back over said same trunk to link the calling line to the called line, means for thereon freeing the trunk while leaving the connection of subscribers continuing, and switches at the substations of lines so connected for rendering them idle when disconnection is desired.

32. A telephone system including telephone lines, two telephone exchanges, terminals of part of said lines at each exchange, trunk lines interconnecting said exchanges, means for automatically extending a call initiated at one exchange to the other exchange over an idle trunk, and mechanism controlled by an operator at said other exchange for working back over the same trunk to complete the connection from terminals of the calling line to terminals of the called line.

33. A telephone system including telephone lines, two telephone exchanges, terminals of part of said lines at each exchange, trunk lines interconnecting said exchanges, means for automatically extending a call initiated at one exchange to the other exchange over an idle trunk, and mechanism controlled by an operator at said other exchange for working back over the same trunk to complete the connection from terminals of the calling line to terminals of the called line with means for freeing the trunk.

34. A telephone system including a main exchange and a sub-exchange, telephone lines terminating in said exchanges, trunk lines connecting said exchanges adapted to be employed for connecting together a telephone line terminating in the main exchange and one terminating in the sub-exchange, means for using said trunk line as an impulse transmitting medium to cause automatic connection of two lines terminating in said sub-exchange, with means for freeing said trunk line for further use when employed as said medium as soon as connection is established.
35. A telephone system including telephone lines, automatic selecting mechanisms at outlying points for interconnecting said lines, a central station having operators' positions, means responsive to initiation of a call for operating one of said mechanisms to connect with the calling line, means for thereon displaying a signal at an operator's position, operators' apparatus for transmitting directive impulses to another of said mechanisms in connecting the calling line with a called line, and a switch for disconnecting said apparatus from said last-mentioned mechanism after its operation.
36. A semi-automatic telephone system including a plurality of exchanges, having telephone lines, trunk lines interconnecting said exchanges, operators' switchboards at some of said exchanges, special impulse trunks extending from each exchange to an operator's switchboard, selective switches directly operable responsive to currents over said impulse trunks to connect calling to called lines, automatic means for connecting calling lines with said impulse trunks, and automatic means for freeing an impulse trunk as soon as a connection between a calling and a called line is established.
37. In a telephone exchange system, the combination with a group of primary trunks, of a group of key-sets, intermediate trunks interposed between said primary trunks and key-sets, and means whereby a primary trunk is connected to an intermediate trunk, and additional means whereby said intermediate trunk is connected to a key-set of the group, substantially as set forth.
38. In a telephone exchange system, the combination with a plurality of groups of primary trunks, of a plurality of key-sets, and means comprising groups of intermediate trunks interchangeable with said key-sets whereby any primary trunk in the said plurality of groups can become associated with any one of said key-sets, substantially as set forth.
39. In a telephone exchange system, the combination with a plurality of calling subscribers' lines, of a plurality of groups of primary trunks, a group of tertiary trunks and associated key-sets, and means for connecting the primary trunks with said subscribers' lines, means comprising groups of secondary trunks interposed between said primary and tertiary trunks whereby any one of the plurality of calling subscribers' lines can become associated with the first i.e. key-set of said group, substantially as set forth.
40. In a telephone exchange system, the combination with a plurality of calling subscribers' lines, of a plurality of key-sets, and means comprising primary, secondary and tertiary selecting mechanisms whereby any calling subscriber's line is connected to any one of said key-sets, substantially as set forth.
41. In a telephone exchange system, the combination with a plurality of groups of primary trunks, of a plurality of key-sets, and means comprising groups of intermediate trunks independent of said key-sets whereby any primary trunks in the said plurality of groups of primary trunks can become associated with any one of said key-sets, substantially as set forth.
42. In a telephone exchange system, the combination with a plurality of groups of primary trunks, of a plurality of key-sets, and means comprising groups of intermediate trunks interchangeably associated with said groups of primary trunks and said key-sets whereby any primary trunk can become associated with any one of said key-sets, substantially as set forth.
43. In a telephone exchange system, the combination with groups of primary trunks, of a plurality of key-sets, groups of trunks intermediate of said primary trunks and key-sets, controlling means whereby one of said key-sets may be exclusively associated with one of said primary trunks through the medium of one of said intermediate trunks, substantially as set forth.
44. In a telephone exchange system, the combination with groups of primary trunks, groups of key-sets, and groups of trunks intermediate of said primary trunks and key-sets, of controlling means whereby but a single key-set is connected to a single primary trunk through a single intermediate trunk, substantially as set forth.
45. In a telephone exchange system, the combination with a plurality of groups of primary trunks, of a plurality of groups of intermediate trunks, of a plurality of key-sets, and means comprising groups of intermediate trunks whereby any primary trunk in the said plurality of groups can become associated with any one of a plurality of said key-sets, substantially as set forth.
46. In a telephone exchange system, the combination with a plurality of calling subscribers' lines, of a plurality of key-sets,

means comprising primary, secondary and tertiary selectors whereby any calling subscriber's line is connected to the first idle one of said key-sets, substantially as set forth.

47. In a telephone exchange system, a plurality of line circuits, automatic switching apparatus for interconnecting the same, an operator's circuit with means to connect the same to the switching apparatus in response to a call, a signal device in the operator's circuit for indicating a call, a sending machine, means controlled by the operator for determining and transmitting current changes from said machine to the switching apparatus, and a guard signal displayed in the operation of said means.

48. In a telephone exchange system, a plurality of line circuits, automatic switching apparatus for interconnecting the same, an operator's circuit with means to connect the same to the switching apparatus in response to a call, a signal device in the operator's circuit for indicating a call, a sending machine, means controlled by the operator for determining and transmitting current changes from said machine to the switching apparatus, and a guard signal displayed in the operation of said means, together with means for retiring the call signal when the guard signal is displayed.

49. In a telephone exchange system, a plurality of line circuits, automatic switching apparatus for interconnecting the same, an operator's circuit with means to connect the same to the switching apparatus in response to a call, a sending machine, means controlled by the operator for determining and transmitting current changes from said machine to the switching apparatus, and a guard signal displayed in the operation of said means.

50. In a telephone exchange system, line circuits, automatic switching apparatus for interconnecting the same, an operator's circuit and switching means for connecting the same with said automatic switching apparatus and with calling lines, an operator's telephone, a self-locking relay controlling the connection of said telephone to said operator's circuit, means for initially closing the circuits of said relay, and a starting key for the automatic switching apparatus adapted to break the locking circuit of said relay and thereby cut off the operator's circuit.

51. In a telephone exchange system, line circuits, automatic switching apparatus for interconnecting the same, an operator's circuit and switching means for connecting the same with said automatic switching apparatus and with calling lines, an operator's telephone, a self-locking relay controlling the connection of said telephone to said operator's circuit, a key under control of the

operator for initially closing the circuit of said relay, and a starting key for the automatic switching apparatus adapted to break the locking circuit of said relay and thereby cut off the operator's circuit.

70

52. In a telephone exchange system, line circuits, automatic switching apparatus for interconnecting the same, an operator's circuit and switching means for connecting the same with said automatic switching apparatus and with calling lines, an operator's telephone, a self-locking relay controlling the connection of said telephone to said operator's circuit, means for initially closing the circuit of said relay in response to a call, and means for unlocking the same automatically thereafter.

75

53. In a telephone exchange system, line circuits, automatic switching apparatus for interconnecting the same, an operator's circuit and switching means for connecting the same with said automatic switching apparatus and with calling lines, an operator's telephone, a self-locking relay controlling the connection of said telephone to said operator's circuits, an operator's switch key for initially energizing said relay, an impulse sender for an automatic switching apparatus, and means controlled by the operator in the use of said sender for unlocking the said relay.

80

54. In a telephone exchange system, line circuits, automatic switching apparatus for interconnecting the same, an operator's circuit and switching means for connecting it to said automatic switching apparatus, and to a calling line, a sending machine, selective means for predetermining impulses to be transmitted from said sending machine through the operator's circuit, a listening-key associated with said selective means, an operator's telephone, a relay controlling the connection of said telephone to the operator's circuit, an energizing circuit for said relay controlled in contacts of said listening key, and a starting key controlling the transmission of impulses from the sending machine to the switches, said key containing contacts controlling said energizing circuit.

90

55. In a telephone exchange system, line circuits, automatic switching apparatus for interconnecting the same, an operator's circuit with automatic switching means for connecting the same to said automatic line connective switching apparatus and to calling lines, a sending machine, and an operator's position equipment comprising a plurality of selective keys adapted to be set so as to predetermine the number and arrangement of impulses to be transmitted from said machine through the operator's circuit to the automatic switching apparatus, a telephone, a listening key associated with the selective keys, together with a relay controlled in the use of said listening key and controlling the

100

110

125

135

- connection of said telephone to the operator's circuit, and a starting key controlling the transmission of impulses to the switching apparatus and also controlling the circuit of said relay, so as to disconnect the operator's telephone when the transmission of impulses commences.
56. A telephone system comprising telephone lines, an operator's link circuit for interconnecting said lines, operator controlled means for applying ringing current and continuing such application to the called line, and means for interrupting such application of ringing current by a control exercised at both the calling and called substations.
57. A telephone system comprising telephone lines, an operator's link circuit for interconnecting said lines, a relay at each end 20 of the link circuit operable over the telephone line connected at that end, means for applying ringing current and continuing such application to the called line, operator controlled means for initiating the operation 25 of said means, and circuit connections including contacts of both of said relays whereby said application of ringing current may be interrupted by a control exercised at both the calling and called substations.
58. A telephone system comprising telephone lines, an operator's link circuit for interconnecting said lines, means for intermittently applying ringing current to the called line, operator controlled means for initiating the operation of said ringing means, and means controlled by either the calling or the called subscriber for disconnecting the ringing current from the called subscriber's line.
59. A telephone system comprising a calling subscriber's and a called subscriber's line, an operator's link circuit for connecting said lines, operator controlled means for applying ringing current to the line of the called subscriber, and means controlled by either of said subscribers for disconnecting said ringing current from said called subscriber's line.
60. A telephone system, comprising telephone lines, an operator's link circuit for connecting said lines, means for intermittently applying ringing current to the called line, electromagnetic means controllable at the substation of the calling line for disassociating his line from the said link circuit, and means responsive to such disassociation for interrupting the application of ringing current to the line of said called subscriber.
61. A telephone system comprising telephone lines, an operator's link circuit for connecting said lines, means included in said link circuit for intermittently applying ringing current to the called line, a disconnect relay for disconnecting the calling subscriber's line from the link circuit, and means controlled by said disconnect relay for interrupting the application of ringing current to said called subscriber's line.
62. A telephone system comprising a pair 70 of telephone lines, an operator's link circuit for connecting said lines, means included in said link circuit for applying ringing current to one of said connected lines, a disconnect relay controlled at the substation of the other of said lines for disassociating said last line and said link circuit, and means controlled by said disconnect relay for disconnecting the ringing current from the first one of said lines.
63. A telephone system including a calling subscriber's line and a called subscriber's line, an operator's link circuit for connecting said lines in conversational circuit, a source of ringing current, means for intermittently applying said ringing current to the said called line, an operator's switch for initiating the operation of said intermittent means, and means controlled by the calling subscriber for causing the cessation 80 of said intermittent means.
64. A telephone system including a calling subscriber's telephone line and a called subscriber's telephone line, an operator's link circuit for connecting said lines in conversational circuit, a source of ringing current, operator controlled means for applying said ringing current to the line of the called subscriber, and means controlled by the calling subscriber for disconnecting said source of 90 ringing current from said called subscriber's line.
65. A telephone system including a calling and a called subscriber's line, an operator's link circuit connecting said lines in conversational circuit, a source of ringing current, means for intermittently applying said ringing current to the called subscriber's line, operator controlled means for initiating the operation of said ringing means, and electromagnetic means controlled by the calling subscriber for preventing the intermittent application of ringing current to the called subscriber's line.
66. A telephone system including a calling subscriber's line and a called subscriber's line, an operator's link circuit provided with a pair of terminals for connecting said lines, a source of ringing current, operator controlled means for connecting said ringing current to the said called subscriber's line, a relay controlled over the calling subscriber's line, and means controlled by said relay for preventing a further application 115 of ringing current to the said called subscriber's line.
67. A telephone system including a calling subscriber's telephone line and a called subscriber's telephone line, an operator's link circuit for use in connecting said lines, a 120

source of ringing current, a relay adapted to be operated intermittently to connect said ringing current to said called subscriber's line, a ringing control relay controlling the operation of said first relay, means for operating said ringing control relay to initiate the operation of said first relay, and electromagnetic means controlled by the calling subscriber for deenergizing said ringing control relay to prevent further operation of said first relay, thereby preventing further intermittent applications of ringing current to the said called subscriber's line.

68. In a telephone system, the combination of a calling telephone line, substation apparatus thereon, a called telephone line, a signal on said line, a main station, link conductors at the main station for connecting the telephone lines together, a switching device for connecting the link conductors to the called line, a signaling generator at the main station, means to connect said generator to said signal, including said called telephone line, a signaling key including key contacts controlling the connecting means and mechanism, operable independently of said switching device and substation apparatus for relieving such key contacts from the control of said connecting means.

69. In a telephone system, the combination of a main station, a telephone line leading to the main station, a signal on said line, link conductors at the main station for connecting telephone lines together, a signaling generator at the main station adapted to be connected to and to operate the signal on the telephone line, a key associated with said link conductors controlling the connection of said generator to said signal and manually controlled means for automatically disassociating said key from said link conductors after the generator has been connected to the signal.

70. In a telephone system, the combination of telephone lines, a subscriber's signal on one of said lines, link conductors for connecting the lines together, an answering switch and a calling switch for connecting the link conductors to telephone lines, a source of current for supplying current to operate said signal, conductors to connect said source to the line to which said signal is connected, a key switch common to a plurality of link conductors normally having no control over said conductors, wires normally connected to said keys and leading to a plurality of other link conductors, means controlled by the answering switch for assigning to said key control over said conductors and means for removing control over said conductors from said key.

71. In a telephone system, the combination of a signaling circuit, a plurality of sources of current, each adapted to be connected in said circuit, one normally con-

nected in said circuit, a relay controlling the connection of each of said sources in said circuit, another source of signaling current adapted to be connected in said circuit, all of said relays jointly controlling the connection of said last named source in said circuit and means controlling said relays.

72. In a telephone system, the combination of a signaling circuit, a plurality of sources of current, each adapted to be connected in said circuit, one normally connected in said circuit, a relay controlling the connection of each of said sources in said circuit, a key controlling each of said relays, a third source of signaling current adapted to be connected in said circuit, connecting means including all of said relays controlling the connection of a third source in said circuit and another ringing key controlling all of said relays.

73. In a party-line telephone system, a called line, a connector for seizing said line, a line relay for said connector energized when connection is extended to said connector, a second relay controlled by said line relay, a plurality of ringing generators for supplying current to the called line, a series of relays for selecting one of said ringing generators, and a circuit for said last-mentioned relays controlled by said second relay.

74. In a telephone system, the combination of a telephone line, a source of signaling current, conductors including a switch for connecting said source to said line, a signaling relay controlling said conductors, a signaling key, apparatus controlled by said switch and operated when said switch is closed for placing said relay under the control of said key and electromagnetic mechanism controlled by said key for removing said relay from the control of said key.

75. In a telephone system, the combination of a telephone line, a source of signaling current, means including a switch for connecting said source to said line, a signaling relay controlling said connecting means, a signaling key, apparatus controlled by said switch after said switch is operated for placing said signaling relay under the control of said key and a second relay controlled by said key for removing said signaling relay from the control of said key.

76. In a telephone system, the combination of a ringing circuit including a switch, a relay controlling the ringing circuit, a ringing key, a circuit for the relay controlled by the ringing key, a second relay adapted to remove the control of the ringing relay winding from the key and means including said key and said switch controlling said second named relay winding.

77. In a combination, a variably adjustable sender, a plurality of switching devices

- operable in accordance with the adjustment of said sender, a relay, an energizing circuit for said relay controlled by said sender, means operable when said relay is energized 5 for operatively associating one of said devices with said sender, and means operable upon the initial deenergization of said relay for operatively associating another one of said devices with said sender.
- 10 78. A telephone system comprising telephone lines, an operator's link of circuit for interconnecting said lines, operator controlled means for applying ringing current and continuing such application to the 15 called line, and means for rendering such application of ringing current ineffective by a control exercised at both the calling and called substations.
79. A telephone system comprising telephone lines equipped with ringers, an operator's link circuit for interconnecting said lines, means for intermittently operating the ringer at the called substation, operator controlled means for initiating the operation of said ringer, and means controlled by either the calling or called subscriber for preventing further operation of said 25 ringer at the called substation.
80. In a telephone system comprising a 30 plurality of telephone lines divided into groups of lines, trunk lines interconnecting the groups, selective mechanism associated with each trunk for extending connections from a calling line associated with the trunk to called lines, impulse sending mechanism common to trunks terminating in different groups of lines, and means responsive to connection of a calling line to the associated trunk to effect controlling connection between said impulse sending mechanism and the selective mechanism of the seized trunk.
81. In a telephone system comprising a plurality of telephone lines divided into groups of lines, trunk lines interconnecting the groups, selective mechanism associated with each trunk for extending connections from a calling line associated with the trunk to called lines, impulse sending mechanism common to trunks terminating in different groups of lines, and means responsive to connection of a calling line to the associated trunk to effect controlling connection between said impulse sending mechanism and the selective mechanism of the seized trunk, and secondary trunks for extending connection under the control of said sending mechanism from said first named trunks to called lines.

In testimony whereof I affix my signature.

EDWARD E. CLEMENT.
